PHONOGRAPH

Charles W. Dann, East Orange, N. J., assignor to
 Thomas A. Edison, Incorporated, West Orange,
 N. J., a corporation of New Jersey

Application June 25, 1938, Serial No. 215,754

32 Claims. (Cl. 274—17)

This invention relates to phonographs, and especially to those of the type intended for the recordation, or recordation and reproduction, of dictation, speeches, conferences and the like.

It is an object of the invention to provide a phonograph of the type described which is small, light and compact.

It is an object to provide a phonograph of the type described which is highly flexible in arrangement, to permit its use as a single unit in an exposed place or in a moderate-sized enclosure, and as a plurality of yet smaller units in small-sized enclosures such as shallow desk drawers and the like.

It is an object to provide a phonograph of the type described employing and characterized by the advantages of electrical recordation and reproduction.

It is an object to provide a phonograph of the type described, the use of which will require a very small number of operations by the operator. It is an allied object to provide such a phonograph wherein the operation of change of records will occasion the automatic performance of many other operations.

It is an object to provide a phonograph of the type described, the advantages of which are attained economically. It is an allied object to form and arrange the components so that they may be constructed of cheap materials and otherwise at low cost. It is an allied object to avoid the necessity for attractively finishing many individual components, as well as to provide a maximum protection of the components from injury and dirt.

It is an object to provide a substantially fully enclosed phonograph without impairing its ready manipulability or the positive awareness of the operator of the condition of the machine at any instant, as to adjustment, extent of recorded and unrecorded record portions, and the like.

It is an object to provide an improved phonograph frame structure.

It is an object to provide an improved translating device carriage, advance device therefor, and combination of carriage with advance device.

It is an object to provide an improved automatic return action for components which under normal circumstances must be returned to initial position upon each change of records. It is an object to prevent the return of the advance device, or other movement thereof, excepting under proper conditions.

It is an object to provide improvements in and

operative simplifications of the control of the translating device and its components, the carriage, the advance device, the record support, and the like, both individually and in various collective senses.

It is an object to insure the correct conditioning of the phonograph at the start of its operation upon a freshly mounted record.

It is an object to provide a phonograph of the type described which, while primarily adapted for recordation, is readily and positively converted for simple reproducing use.

It is an object to provide improvements in the electrical and mechanical association of an electronic amplifier with the rest of the phonographic apparatus.

It is an object to provide improved means for detachably coupling separate parts of the apparatus.

20 It is a general object to provide a generally improved phonograph of the type described.

Other and allied objects will more fully appear from the following description and the appended claims.

25 In the detailed description of my invention, hereinafter set forth, reference is had to the accompanying drawings, of which:

Figure 1 is a perspective view of a complete phonograph equipment according to my invention;

30 Figure 2 is a top plan view of the phonograph proper without its cover, for example in an adjustment for recordation, a few of the bottom parts being omitted for the sake of clear illustration;

Figure 2a is a fragmentary horizontal cross-sectional view taken centrally through the large diameter cylinder 95 appearing in plan in the upper lefthand corner of Figure 2;

35 Figure 3 is a front elevational view of the phonograph, adjusted for reproduction of matter already recorded, some of the more rearward parts being omitted;

Figure 3a is a fragmentary horizontal cross-sectional view taken on the line 3a—3a of Figure 3;

40 Figure 4 is a vertical cross-sectional view of the phonograph taken substantially along the line 4—4 of Figure 2, but with the phonograph in a neutral adjustment, a few of the most rearward parts being omitted;

45 Figure 5 is a bottom plan view of the phonograph, for example at the termination of recordation upon a record, some of the upper carriage components being omitted;

50

Figure 6 is a rear elevational view of the phonograph, supported on the amplifier 2, with the phonograph in a stopped condition;

Figure 7 is a vertical cross-sectional view of the phonograph, again supported on the amplifier, taken substantially along the line 1—1 of Figure 2 to show the carriage but not the advance slide, and illustrating the phonograph during the process of the return of the carriage to its initial position;

Figure 8 is a fragmentary rear elevational view of the phonograph and amplifier covers, the phonograph being again supported on the amplifier;

Figure 9 is a lefthand end view of the phonograph with the lefthand end plate 32 removed, illustrating the phonograph adjusted for recordation or for reproduction but in a stopped condition, a few components being omitted from the lower central portion of the figure for the sake of clear illustration;

Figure 9a is a fragmentary vertical cross-sectional view taken substantially along the line 9a—9a of Figure 10a, illustrating components omitted from Figure 9 in the positions which they would occupy in that figure;

Figure 10 is a vertical cross-sectional view, taken substantially along the line 10—10 of Figure 2 to show the advance slide but not the carriage, and illustrating the phonograph during the process of the return of the carriage to its initial position;

Figure 10a is a fragmentary horizontal cross-sectional view, taken very approximately along the line 10a—10a of Figure 10, and illustrating the lower rear lefthand corner portion of the phonograph just as the process of carriage return is being completed;

Figure 11 is a fragmentary view similar to Figure 9a or to a portion of Figure 10, but illustrating its components after the completion of the process of carriage return but before the phonograph has again been started;

Figure 12 is a righthand end view of the carriage, with portions of the righthand end member 71 removed, illustrating a recordation adjustment;

Figure 13 is a staggered vertical view taken through the carriage looking from the right, illustrating a reproduction adjustment, the translating device being shown in simplified elevation;

Figure 14 is a vertical cross-sectional view of the carriage, taken principally along the line 14—14 of Figure 12, and illustrating a neutral adjustment;

Figure 15 is a partial vertical cross-sectional view of the central carriage components, taken principally along the line 15—15 of Figure 12;

Figure 16 is a vertical cross-sectional view of the translating device only, taken principally along the line 16—16 of Figure 15, the vibration damper 305 being omitted;

Figure 17 is a horizontal cross-sectional view of the carriage, taken principally along the line 17—17 of Figure 12, and illustrating a neutral adjustment;

Figure 18 is a vertical front view of the second cam plate 371, in neutral position;

Figure 19 is a vertical front view of the auxiliary cam plate 401, in inactive position;

Figure 20 is a vertical cross-sectional view of the lower portion of the carriage, taken principally along the line 20—20 of Figure 21;

Figure 21 is a horizontal cross-sectional view of the lower portion of the carriage, with the translating device omitted, taken substantially

along the line 21—21 of Figure 20, and illustrating the components during operation of the phonograph but with a neutral adjustment;

Figure 22 is a partial vertical cross-sectional view taken principally along the line 22—22 of Figure 21, showing the relationship of the auxiliary cam plate to certain of the rear carriage components;

Figure 23 is a partial vertical cross-sectional view taken principally along the line 23—23 of Figure 21;

Figure 24 is an enlarged, partial horizontal cross-sectional view taken substantially along the line 24—24 of Figure 22;

Figure 25 is a partial vertical cross-sectional view taken principally along the line 25—25 of Figure 24, and indicating various positions occupied by certain of the components under different conditions of adjustment;

Figure 26 is a lefthand elevational view, with a small portion in section, of the latch lever 435 and associated components, illustrating two positions which may be assumed by that latch lever;

Figure 27 is a partial vertical cross-sectional view taken principally along the line 27—27 of Figure 24;

Figure 28 is a vertical cross-sectional view of the central and top righthand portions of the carriage and advance slide system, taken vertically through the carriage rod 70;

Figure 29 is a righthand elevational view of the phonograph, illustrating the phonograph after a record has been mounted on the mandrel but before the next ensuing starting of operation of the phonograph;

Figure 30 is a simplified schematic wiring diagram of the electrical connections of the phonograph;

Figure 31 is a righthand inside elevational view of the bottom part of the lefthand end of the cover 6 in position on the phonograph;

Figures 32a and 32b are fractional perspective views respectively of the lower lefthand front corner of the cover 6 and of the forward end of the associated coupling slide, separated from their normal relationship;

Figures 33a and 33b are fractional perspective views respectively of the lower lefthand rear corner of the cover 6 and of the rear end of the associated coupling slide, separated from their normal relationship; and

Figure 34 is a lefthand end view of the lower rear portion of the phonograph, with the end plate 21 shown only in dash-dot lines to expose a dashpot device 590 which I prefer to employ but which has been omitted from other figures in the interest of simplicity of illustration.

Figure 1 illustrates in perspective a complete electrical recording and reproducing phonograph equipment according to my invention, with all the necessary controls therefor; from this figure may be seen the extreme compactness, full encasement and protection of components, and simplicity of control and of appearance, which characterize the equipment. Four units are shown: the phonograph proper as 1, an amplifier as 2, a handpiece (for sound collection and dispersal) as 3, and a stand for the handpiece as 4, the several units being electrically interconnected by appropriate thin cabling such as 5. Both phonograph 1 and amplifier 2 are of very small height; as shown in Figure 1 (and in later Figures 6, 7 and 8) the amplifier 2 is in inverted position, forming a base for the phonograph 1. It will be understood, however, that the phonograph and

amplifier may when desired be otherwise disposed—the amplifier for example upright in the drawer of a desk, the phonograph being disposed in that or another drawer or on top of the desk, or the like, the small size of these units permitting a wide choice of their dispositions and affording a high degree of portability of the complete equipment.

Attention being directed particularly to the phonograph 1, it will be seen from Figure 1 that a unitary cover 6 substantially completely encloses it. The cover 6 is formed with a large, approximately circular hole 7 in its right-hand end, exposing the end of the mandrel (hereinafter more fully mentioned) and permitting the mounting of a cylindrical record on the mandrel and its removal therefrom. The hole 7 also exposes a lever 8 hereinafter more fully described; this lever is provided with a hinged fingerpiece 9 which normally extends outwardly through the cover hole 7, but which may be folded up to a vertical position to permit the lowering and raising of the cover. The cover 6 is formed with a slot 10 along the bottom of its front, through which slot a carriage 11 extends to terminate in a vertical control plate 12 very slightly spaced forwardly of the front cover surface, the carriage (hereinafter detailedly described) and control plate being arranged for side-to-side travel. Above the slot 10, and on to the righthand end of the cover, the upper front edge of the cover is cut away to expose an elongated annotation-slip holder 13 which extends horizontally from side to side, and inclinedly upwardly from front to back. The top of the cover 6 is provided with a flange portion 14 downhanging toward the holder 13 near the rear of the latter; a small space between the bottom of the flange portion 14 and the holder 13 permits the forward extension over the holder of two pointers—a carriage pointer 16 and an advance pointer 17, hereinafter more fully referred to. The lefthand end of the flange portion 14 may be joined to the front of the cover by a further small flange portion 15 downhanging from the cover top to below the top of the lefthand extremity of the holder 13. The so-described interruptions in the continuity of the cover 6 are the only ones necessary for manipulation or observation of the phonograph.

Frame and mandrel

The components of the phonograph 1 are assembled to a frame which basically comprises two vertical front-and-back extending plates 21 and 22, held to a circumferentially incomplete cylinder 20 at the extremities of the latter. In Figures 2 through 5 plate 21 appears as the righthand end member and plate 22 as an intermediate member relatively near the lefthand end of the machine, the cylinder 20 passing therebetween approximately at mid-position from front back. The circumferential discontinuity of the cylinder 20 is a longitudinal opening 19 in the cylinder wall, of very approximately 90 degrees extent, and disposed toward the front of the machine; its upper edge appears as 19a in Figures 2 and 3 and its lower edge as 19b in Figure 5, but it is best seen in the central front-and-back vertical section of Figure 7. The plate 21 does not cover or close its end of the cylinder 20; the cylinder terminates in a full circular aperture in this plate, as best seen in the righthand end view of Figure 29, and with this aperture the cover hole 7 is aligned when the cover is in

place. The plate 22, however, covers its end of the cylinder (except for a small segment at the discontinuity 19) and, as may be seen best in Figures 2, 4 and 5, is provided with a leftwardly extending boss 23 central of the cylinder. In this boss there is secured, as by set screw 25, the lefthand end portion of a tube 24 extending axially of cylinder 20; and through this tube is rotatably passed a mandrel shaft 26. A mandrel 27 is secured on the mandrel shaft, within the cylinder 20, the latter thus forming an enclosure or shield for the mandrel and for the cylindrical record removably mounted on the mandrel. Such a record, by way of example a wax record, has been indicated in various figures (Figure 4 for example) as R.

The mandrel 21, which may be of a well-known form such as that disclosed in U. S. Letters Patent No. 2,010,717, issued August 6, 1935, on application of Heinrich F. Max Gramann, is not illustrated in detail. It may be pointed out, however, that the mandrel may comprise chuck members 28 (appearing in Figure 4 for example) which are collapsed when no record is on the mandrel, and which automatically expand and internally grip the righthand end of a record which has been slid into place on the mandrel; and that it may comprise a fingerpiece 29 which, if pressed leftwardly when a record is on the mandrel, will cause the collapse of the chuck members and the ejection of the record.

The plate 22 does not itself extend forwardly of the cylinder 20; but from the lefthand extremity of the boss 23 above mentioned there extends forwardly an extension plate 31 having upper and lower arms 31a and 31b, respectively, as best seen in Figure 9. It will be understood that the assembly of plates 21 and 22, cylinder 20, boss 23, and extension plate 31, may be made of die castings.

The frame of the machine may include, in addition to the components just mentioned, another front-and-back extending, vertical plate 32; this may form the lefthand end member of the machine, and may be held spaced away from plate 22 by horizontal spacing means such as top post 33 fractionally shown in Figures 2 through 4) and bottom post 34 (shown in Figures 3 through 5). It may further be tied to the lower plate arm 31b near the front of the machine through a block 35 and post 36, these being integrally formed and secured respectively to 32 and 31b.

The annotation-slip holder 13, into which a slip S may be leftwardly inserted, comprises a trough member 13a terminally secured on the front portions of the tops of plate 21 and upper plate arm 31a; and a platform member 13b secured within, and raised above the bottom of, the trough member 13a. Slip-holding flanges 13c are formed rearwardly from the upturned front of the trough member and forwardly from the rear of the platform member, that trough member front and the platform member extending leftwardly only as far as the cover flange 15.

Motor, etc.

A motor supplying driving power for various functions hereinafter mentioned is shown as 40; this is disposed behind the cylinder 20, to the right of the plate 22. The internal construction of the motor is not shown in detail; but in Figures 5 and 6 there will be seen, largely in dotted lines, lefthand and righthand end members 41 and 42 for the motor assembly. Top and bottom

semi-cylindrical shields 43 and 44 extend from one end member to the other, enclosing and shielding the motor. The lefthand motor end member 41 is secured to the plate 22 through a plurality of short mounting pillars 45. To the righthand motor end member 42 is secured the lefthand end wall 51 of a die-cast housing 50; and from the top of the front surface of this housing there extends upwardly and forwardly an L-shaped lug 46, best seen in Figure 7. This lug overlaps a flat projection 47 formed from the upper rear surface of the cylinder 20; and it is secured thereto by a screw 48, to complete the mounting of the motor. It has been found desirable to keep the entire motor frame and shielding free of electrical connection with the frame of the phonograph; accordingly the lug 46 may be insulated from the projection 47 as by insulation 49 disposed therebetween and around the screw 48, and insulating means may be employed in connection with the securing of the motor end member 41—such as the formation of the pillars 45 as insulating inserts in that end member. At the left of the motor its shaft 39 extends through the end member 41, and through an oversize hole 38 in plate 22 into the space between plates 22 and 32, as seen for example in Figure 2. At the right of the motor the shaft 39 extends, through bearing 52 secured to the end member 42, into the housing 50.

On shaft 39 within the housing 50 is secured a centrifugal fan 53, comprising hub 54, disc 55, and vanes 56, all integrally cast for example. Opposite the fan 53 the rear wall of the housing is provided with a rectangular air duct 58 leading and opening rearwardly, while the bottom wall of the housing is provided with a rectangular air duct 57 leading and opening downwardly. An air path 59 is provided from the interior of the motor into the housing 50 through the housing end wall 51; and at the lefthand extremity of the motor its shields 43 and 44 are provided with air-admitting holes 60. The action of the fan 53 is to suck air through the holes 60, past the motor and through the air path 59, and to expel it through the air ducts 57 and 58, thereby cooling the motor.

In the space 61 within the housing 50 beyond the fan 53 there may be located an electrical-contact type of governor for the motor; this governor, of which the details form no part of the instant invention, appears in purely schematic mechanical illustration in Figure 6, and in dia-grammatic electrical illustration in Figure 30. At the bottom of the housing 50 there may be provided a shelf 62 extending a short distance rightwardly (appearing of course as leftwardly in the rear view of Figure 6). In the space 63 above this shelf and on top of the housing 50 may be disposed the components of an electrical filter system, as schematically indicated at F in Figure 6, interposed, as dia-grammatically indicated at F in Figure 30, in the electrical connections to the motor for the suppression of high-frequency electrical disturbances which may tend to be set up by the motor. The space 63 may be covered and shielded by a generally L-shaped hollow cover 64, this cover being electrically at the potential of the housing 50 and motor 40.

Carriage, advance slide and feed screw.

Attention now being directed to the components in front of the cylinder 20, there will be seen, in Figure 3 for example, a carriage rod 70 passing the full length of the machine at ap-

proximately mid-elevation, and terminally secured in plates 32 and 21. Along this rod there is adapted to move the carriage 11, already mentioned. While the carriage is illustrated and described in detail in and in connection with later figures, its general form will be apparent from Figures 2, 3, 5 and 7. It may include a righthand end member 71 and a lefthand end member 72, each in general vertically disposed in front of the cylinder 20 but extending, in its bottom portion, forwardly through the cover slot 10 and rearwardly to underneath the cylinder 20. The carriage may further include, between members 71 and 72, a top cross portion 73, a rear cross portion 74, and a central cross-portion 75, the latter surrounding and bearing on the rod 70 and having the leftward extension 76 beyond end member 72 (seen in Figure 3) also surrounding and bearing on rod 70. Adjacent the top of the end member 71 the cross portion 73 is thickened and provided with a bevel surface 77 in a plane approximately directed toward the cylinder 20 axis; and in this surface is secured a stud 78 carrying a roller 79 free to rotate on the stud. The periphery of this roller rests against a ridge 80 formed on the outer surface of cylinder 20 adjacent the top of the cylinder opening 19, and rides along this ridge as the carriage is moved along rod 70. The weight of the carriage develops a force tending to rotate it about rod 70, rearwardly above that rod, and the roller 79 and ridge 80 form a bearing which resists that force. To render the carriage secure against rotation in the opposite direction a screw 81 may be passed upwardly through the rear cross portion 74, substantially into contact with a ridge 82 formed on the outer surface of cylinder 20 underneath the cylinder axis.

To the top of the top carriage cross portion 73 in its lefthand half there is secured a plate 69, and from the righthand extremity of this plate there is formed the narrow, flat carriage pointer 16 above stated to extend forwardly over the annotation-slip holder 13. Surrounding the carriage rod 70 at the right of the carriage 11 is a generally cylindrical advance slide 120. In its normal position relative to the carriage, the slide 120 extends leftwardly into a partial annular recess 75a formed in the righthand carriage end member 71 and the central carriage cross portion 75 immediately adjacent the rod 70, this recess extending leftwardly for a minor part of the width of the carriage and being indicated for example in Figure 7. In its normal position, the slide 120 extends rightwardly to bring its righthand extremity only very slightly to the right of the carriage end member 71. The advance slide 120 is normally pushed rightwardly by the carriage 11 as the carriage moves in that direction. Ordinarily the carriage portion immediately in contact with the advance slide 120 is a thin finger 125 carried by the carriage and normally extending downwardly into the carriage recess 75a at the lefthand extremity of that recess; this finger is hereinafter more particularly referred to, but its extremity may be seen in Figure 7 in the recess 75a above the rod 70.

To the righthand extremity of slide 120 is secured an arm 121, seen in Figure 10, extending upwardly and rearwardly from the slide in a vertical plane to terminate in gravity-maintained contact with the upper ridge 80 on cylinder 20. On the lefthand surface of the arm 121 at its upper extremity is formed a thin boss or button

122; when the finger 125 is in contact with the lefthand slide extremity this button is slightly spaced from the surface of the righthand carriage end member 71, as may be seen in Figure 2. From this figure and Figure 10 it may also be seen that a bracket 123 is secured to the arm 121 near the arm extremity, extending first vertically upwardly and then horizontally leftwardly just above the top carriage cross portion 73. On top of the horizontal portion of this bracket there is secured a plate 124 in position such that its lefthand extremity is always spaced from the righthand extremity of plate 89 by a shade more than the spacing of button 122 from carriage end member 71. From the lefthand extremity of the plate 124 there is formed the narrow, flat advance pointer 17 above stated to extend forwardly to over the annotation-slip holder 18.

A feed screw 83 is disposed below and parallel with the rod 70, and against this screw is biased a feed nut 84 carried in the carriage 11, shown in Figure 7, and hereinafter more particularly referred to. At its lefthand end the feed screw 83 passes through and is journaled in the lower plate arm 31b. At its righthand end the feed screw is journaled in the cross portion or base 86 of a U-shaped hanger 85, whose extremities 85a are secured to the plate 21 so that hanger 85 extends leftwardly from that plate; a top view of the hanger 85 appears as Figure 3a. The feed screw 83 is rotated whenever the mandrel 27 is rotated; accordingly, assuming the feed nut 84 in engagement with the feed screw in response to its bias, the carriage 11 is driven slowly rightwardly so that stylus means carried by the carriage and engageable with a record R on the mandrel will traverse a spiral path on the record.

The stylus means and the control system therefor are hereinafter particularly described. It may here be mentioned, however, that those means may comprise a recording stylus and a reproducing stylus; and that that system may comprise a substantially inverted triangular, front-and-back extending fingerpiece or lever 88 in front of the vertical control plate 12 in which the carriage 11 was above stated to terminate at the front of the machine. This fingerpiece or control lever 88 is secured at its bottom to the top of an inverted triangular, side-to-side extending plate 89 spaced slightly in front of the control plate 12—the plate 89 being mounted to be swung in its own plane, and the control lever 88 accordingly being inclinable, to the right and left of the mean position illustrated in Figure 1. When the plate 89 is in its mean position, with the control lever 88 vertical, both styli are disengaged from the record and the feed nut 84 is held, against its bias, away from the feed screw 83—i. e., a neutral adjustment is established. When the control lever 88 and plate 89 are moved to the right (e. g., as in Figure 2) and to the left (e. g., as in Figure 3), recordation and reproduction adjustments are respectively established; in each of these adjustments, excepting as prevented by other means hereinafter described, the respective stylus is engaged with the record and the feed nut 84 is engaged with the feed screw 83.

In Figure 2 the control lever 88 is shown in its recordation position, and the carriage 11 and the advance slide 120 in their normal relationship to each other. If the mandrel 27 and feed screw 83 be rotated, the carriage and advance slide will be driven slowly rightwardly and the record-

ing stylus will traverse the rotating record; that stylus, being vibrated in accordance with sound as hereinafter described, will record that sound on the record as by cutting in the record surface an appropriately modulated groove. If it should be desired to condition the phonograph for the reproduction of matter already recorded on the record, the mandrel and feed screw rotation is first preferably stopped, the control lever 88 is moved into its central or neutral position (disengaging the stylus from the record and the feed nut from the feed screw), the carriage is manually moved leftwardly the desired distance, and the control lever 88 is then moved into its lefthand or reproduction position (engaging the reproducing stylus with the record and the feed nut with the feed screw); the advance slide 120, however, is left at the position which it occupied at the beginning of the manipulations just mentioned. Now when the mandrel and feed screw are again rotated, the carriage will be driven slowly toward the advance slide and the reproducing stylus will traverse the rotating record; the vibrations of that stylus caused by the record groove modulations are translated into sound as hereinafter described. Figure 3 illustrates the phonograph at the beginning of or during its operation for such reproduction, the carriage being assumed to have been moved leftwardly a considerable distance in the conditioning of the phonograph for the reproduction. When the carriage has been driven rightwardly sufficiently to re-establish the normal relationship between it and the advance slide (i. e., when the finger 125 has again come into contact with the lefthand end of the advance slide) the reproducing stylus will have traversed all the matter recorded before the conditioning of the phonograph for reproduction; the phonograph may then be re-conditioned for recordation by the movement of the control lever 88 from its reproduction position back into its recordation position.

Mandrel and feed screw rotation

The power of the motor 40 is made available for various functions in the phonograph through the medium of a rotatable pulley or hub 91 driven by the motor, best seen in Figures 2, 2a and 9. Thus between the plates 22 and 32, a little above and forward of the motor shaft 39, is journaled a horizontal rod 90, and on this rod is secured the hub 91 abovementioned; this hub may be of length about half the distance between plates 22 and 32, and may be held relatively near the plate 32. At the righthand end of hub 91 is formed a disc 94 of relatively large diameter; and at the periphery of this disc is formed a rightwardly extending annular flange or cylinder 95. The motor shaft 39 extends to within this cylinder, and on its extremity is secured the small pulley 96. Within the cylinder is located a mechanism constantly coupling the pulley 96 to the inside surface of the cylinder. The fundamental element of this mechanism is a coupling roller 97 of rubber or other insulating and resilient composition, disposed diagonally forward of and below the pulley 96 and carried by the forward bifurcated extremity of a curved arm 98. The rear bifurcated extremity of this arm is pivotally secured to the lower extremity of a lever 99 which is pivotally mounted on a stud 100 extending leftwardly from plate 22, these elements being best seen in Figures 2a and 10. The upper extremity of the lever 99 is constantly biased forwardly by

a spring 103 tensioned between a pin 101 in that lever extremity and a pin 102 secured in the plate 22; this maintains a bias of the coupling roller 97 against both the pulley 96 and the inside surface of cylinder 95, in spite of any possible wear of the roller. It will accordingly be understood that the cylinder 95 and hub 91 will be rotated whenever the motor 40 is operated, though at reduced angular velocity in view of the relative diameters of pulley 96 and cylinder 95. Among other things, the mandrel 27 and feed screw 83 are driven by the hub 91, being clutchable thereto and de-clutchable therefrom to control their rotation, as may now be described.

The mandrel shaft 26 is extended, to the left of the extremity of tube 24, to a bearing 104 in plate 32, as best seen in Figure 4. Adjacent the bearing 104 there is secured on the shaft 26 a hub 106 extending rightwardly substantially to the extremity of tube 24. At about the center of the hub 106 there is formed a disc 107 of relatively large diameter; and at the periphery of this disc is formed a rightwardly and leftwardly extending annular flange or short cylinder 108. This cylinder is in front-and-back alignment with a major portion of the hub 91 abovementioned, and is spaced slightly forwardly of the latter, as seen best in Figure 9. The cylinder 108 is driven from the hub 91 through the intermediary of a clutch roller 110 of rubber or other resilient composition, which may be selectively moved into joint engagement with cylinder 108 and hub 91 or out of such engagement, as hereinafter more particularly described. It will be understood that during such engagement the mandrel 27 will be rotated by the hub 91, though at a reduced angular velocity in view of the relative diameters of hub 91 and cylinder 108. In Figures 9 and 10 there have been indicated by arrows the typical directions of rotation of the several rotary members described in this and the preceding paragraph.

The feed screw 83 is slowly rotated simultaneously with mandrel rotation through the intermediary of a train of gears best seen in Figures 2 and 9. This train comprises a gear 111 secured on hub 106 near the righthand extremity of the latter; a larger gear 112, engaging gear 111, and carried on a stud 116 secured in lower plate arm 31b in front of and a little below shaft 26; a small gear 113 also carried on stud 116 and securely connected with gear 112, to rotate therewith, through a collar 117 therebetween; a coupling gear 114, engaging gear 113, and carried on a stud 118 secured in lower plate arm 31b in front of and a little below stud 116; and a gear 115, engaging the coupling gear 114, and secured on the lefthand extremity of the feed screw 83 just to the left of the lower plate arm 31b.

Control of mandrel and feed screw rotation

As seen in Figures 9 and 2, the clutch roller 110, which controls the mandrel and feed screw rotation, is carried by a vertical fork member 130 hanging down between the hub 91 and cylinder 108; near the bottom of this fork member, and below the center line between that hub and that cylinder, is a horizontal cross pin 131 on which the clutch roller 110 is rotatably mounted. Near its top extremity the fork member 130 is curved slightly rearwardly, and at that extremity it is pivotally held on a horizontal cross pin 136 in the bifurcated forward extremity of a horizontal lever 137; this lever is intermediately pivoted on a horizontal stud 139 extending rightwardly from

the plate 32. The fork member 130 has a cross member 132 a little above the roller 110; and a spring 133, tensioned between the cross member 132 and a horizontal pin 134 secured in plate 32 thereabove, biases the fork member upwardly and the clutch roller 110 into its effective position of joint engagement with hub 91 and cylinder 108. The roller 110 may be moved out of such engagement (though remaining engaged with the cylinder 108) by upward movement of the rear extremity of lever 137. So to move the lever there is pivotally mounted on the stud 139, in straddling relationship to the lever, the bifurcated forward extremity of a horizontal arm 140; between the side portions of this arm underneath the rear extremity of lever 137 is a cross member or web 141, against which there is adapted to impinge the lower end of a vertical screw 138 carried in that lever extremity. When the rear extremity of arm 140 is sufficiently low the web 141 is out of contact with screw 138, clutch roller 110 obeys its bias and engages hub 91 and cylinder 108, and the mandrel and feed screw are rotated. When the rear extremity of arm 140 is sufficiently raised the web 141 impinges against screw 138, raising the rear lever extremity, forcing fork member 130 downwardly, disengaging the clutch roller, and stopping the rotation of the mandrel and feed screw. The bottom surface of the upper extremity of the fork member 130 may be formed with a concave heel 135, which when the member 130 is lowered is pressed downwardly into contact with a resilient stop, comprising a resilient cylindrical pad 142 extending rightwardly from the plate 32 in an appropriate position.

The position of the rear extremity of arm 140 may be controlled by a solenoid assembly positioned therebeneath, best seen in Figures 6, 2 and 9; this assembly may be supported by a vertical plate 145 secured to and forming a rearward extension of plate 32. To this plate 145 may be secured a lower rectangular iron frame 146 and an upper like frame 147, in vertical alignment with each other; and within these frames respectively may be held the vertical solenoids 148 and 149. From the bottom horizontal member of the lower frame 146 a core member 150 extends upwardly a short distance axially within solenoid 148; and from the top horizontal member of the upper frame 147 a core member 151 extends downwardly a short distance axially within solenoid 149. The top horizontal member of the lower frame 146 and the bottom horizontal member of the upper frame 147 are suitably apertured to permit a common vertical iron plunger 152 to extend axially between and partially into the two solenoids, the plunger 152 having a considerable range of vertical movement between the two core members 150 and 151. The top core member 151 is centrally apertured to pass a thin coupling rod 153, whose lower extremity is secured in the upper end of the plunger 152 and whose upper extremity carries a horizontal pin 154 extending both rightwardly and leftwardly. The rear extremity of arm 140 is bifurcated horizontally to embrace the vertical coupling rod 153; and on each side of that rod the arm extremity is bifurcated vertically to embrace the horizontal pin 154. It will be understood that when the lower solenoid 148 is actuated the plunger 152 will be attracted into a downward position, causing rod 153 and the rear extremity of arm 140 to assume downward positions and the clutch roller 110 to be engaged as abovementioned; and that when the upper sole-

noid 149 is actuated the plunger 152 will be attracted into an upward position (as illustrated in Figures 6 and 9), causing the assumption of upward positions by rod 153 and by the rear extremity of arm 140 and the disengagement of the clutch roller 110. In order that each of the two positions of plunger 152, arm 140 etc. may be positively maintained after having been established, a sufficiently strong toggle spring device 155 may be connected between a pin 156 extending rightwardly from plate 145 (near its rear top corner) and a pin 157 extending leftwardly from arm 140 somewhat forwardly of pin 156.

In view of their respective influences on mandrel (and feed screw) rotation, the lower and upper solenoids 148 and 149 may respectively be termed "starting" and "stopping" solenoids. They are arranged for alternate, momentary actuations through the medium of a single-pole double-throw switch, which upon the actuation of either solenoid breaks the power circuit to it and closes that power circuit to the other. This switch, best seen in Figure 6, is assembled to the rear of a vertical, side-to-side extending plate 159, this plate being held at the right of frames 146 and 147 by brackets 160 and 161. The two throw-contacts of the switch are shown at 162 and 163, respectively carried near the tops of vertical springs 164 and 165 secured to and extending upwardly from the lefthand and righthand sides respectively of an insulating block 166, this block being secured against the lower rear surface of plate 159. As will appear from the diagrammatic Figure 30, contact 162 is electrically connected in series with starting solenoid 148, and contact 163 in series with stopping solenoid 149. The pole of the switch is shown as a pair of contacts 167 on opposite sides of a vertical lug 168 folded rearwardly from the lower lefthand edge of a pivoted vertical arm 170 disposed parallel with and behind plate 159; the contacts 167 are electrically connected together but are insulated from lug 168 as by insulation 169. The arm 170 is pivoted, at its top extremity, for movement in its own plane, as on a horizontal pin 171 extending rearwardly from the upper portion of plate 159 to a lug 172 folded rearwardly and leftwardly from the righthand edge of plate 159 near its top.

The arm 170 is moved, to throw the switch, by the plunger 152; this movement is effected through the medium of a lever 173 intermediate pivoted on a horizontal pin 177 extending rearwardly, from a leftward projection 159a of the central portion of plate 159, to a lug 179 folded rearwardly and upwardly from the bottom of that projection. A bushing 178 around the pin 177 in front of the lever 173 holds the latter rearwardly against lug 179. The lefthand extremity of the lever 173 is vertically bifurcated to embrace a lug 180 extending rearwardly from a horizontal disc 181 which is secured about the plunger 152 between the solenoids, so that the lever 173 is rocked in a vertical plane by the plunger movement. The lever 173 moves the arm 170 through the medium of an auxiliary lever arm 174 integral with and extending upwardly from the center of the lever 173, and a toggle spring 184; this toggle spring is terminally connected to a pin 185 extending forwardly from the upper extremity of lever arm 174 and to a pin 186 extending rearwardly from arm 170 above pin 185. The righthand extremity of lever 173 is folded forwardly to form a small lug 175, and from the arm 170 there ex-

tends rearwardly a small lug 176, the vertical path of lug 175 and the horizontal path of lug 176 crossing each other. Lug 175 therefore interferes with the movement of lug 176 in either direction, preventing any switch-throwing movement of arm 170, until the substantial completion of the movement of the plunger (either up or down); this prevents the premature opening of the power circuit to that solenoid which is causing the plunger movement. The plunger movement is conveniently limited and silenced by bumper discs 182 and 183 of soft material respectively above and below the disc 181 above-mentioned. The arrangement of the switch is of course such that the actuation of the starting solenoid 148 will move the arm 170 rightwardly to bring and leave the switch pole (one of the contacts 167) against contact 163, thus open-circuiting the starting solenoid 148 at contact 162 and preparing the stopping solenoid 149 for next actuation; and vice versa.

Return mechanism

There has been described the manual leftward movement of the carriage, to such extent as desired, without the advance slide 120, when it is desired to reproduce matter already recorded on a record in the phonograph. It will be understood, however, that there is necessary a leftward movement, or return, of both the carriage and the advance slide to their initial positions when a fresh record is mounted on the mandrel. In the phonograph according to the instant invention there is incorporated a power-driven means for effecting this return. This means may be driven from hub 91 through a second clutch roller engageable with that hub; there may first be described the structure of the return means and its operation when that roller is engaged, attention thereafter being given to the control of the engagement of that roller. The return means is immediately associated with the advance slide 120, and operates directly upon that slide to cause its leftward movement; the slide in that movement pushes the carriage leftwardly, so that both are returned together. The return means is in the form of a chain-and-sprocket drive, and its major portions are best seen in Figure 3.

Two sprockets are provided near the respective ends of the phonograph; these are centered at the lever of the feed screw 83, and lie in a single vertical plane passing through the feed screw axis. The righthand sprocket 190 is contained within the hanger 85 above-mentioned; it is rotatably mounted on a horizontal cross pin 189 extending in a front-and-back direction between the sides of the hanger, and may project somewhat into a vertical slot 188 formed in the plate 21 centrally of the hanger. The lefthand sprocket 191 is rotatably mounted on a stud 194 extending forwardly from block 35 above-mentioned, the lower front portion of plate 32 being cut away (as indicated at 32a in Figure 3) to clear this sprocket. From the bottom of the advance slide 120 at its lefthand extremity there hangs down a pair of front-and-back aligned lugs 195 (as seen in Figure 10); a chain 196, secured to a horizontal cross pin 195a between these lugs, passes leftwardly therefrom to sprocket 191, downwardly around that sprocket, rightwardly underneath the feed screw 83 to the sprocket 190, upwardly around that sprocket, and leftwardly back to cross pin 195a. A tensioned spring 197 may be interposed in the lower por-

tion of the chain 196 to maintain the latter taut. Sprocket 190 is always free to rotate; and sprocket 191, although coupled to other mechanism as will next appear, is ordinarily likewise free to rotate. Thus as the carriage and advance slide are driven rightwardly by the feed screw the chain 196 slowly idles over the two sprockets.

Reference now being had especially to Figures 5 and 9, it will be seen that behind sprocket 191 on stud 194 there is provided a gear 192; this is secured to sprocket 191 through a collar 193 therebetween, the gear and sprocket and collar being rotatable as a unit on the stud. In the block 35 below the stud 194 there is journaled a horizontal, front-and-back extending shaft 198; and on the forward extremity of this shaft, just in front of the block 35, there is secured a gear 199 engaging the gear 192. The shaft 198 extends rearwardly below the cylinder 108, and is journaled in another block 200 secured to the righthand surface of plate 32 at the bottom and somewhat behind the horizontal center of that plate. On the rear extremity of the shaft 198, just behind the block 200, is secured a bevel gear 201 (best seen in Figure 5), which is engaged by a second bevel gear 202 having a horizontal, side-to-side extending axis. This bevel gear 202 is secured to a simple gear 203 of larger diameter immediately to its left, and to a small hub 204 immediately to its right, the assembly 202—203—204 being rotatably mounted closely adjacent plate 32 on a rod 205 which extends horizontally between plates 32 and 22 below the cylinder 95. Just to the right of the small hub 204, on the rod 205, there is rotatably positioned another hub 224 forming a portion of a casting which is hereinafter more particularly described, but which may here be mentioned to include an arm 225 extending upwardly and somewhat rearwardly from hub 224 to terminate beneath, and to the rear of the center of, hub 91 abovementioned. Near the top extremity of this arm 225 there is secured a leftwardly extending horizontal stud 208. On this stud there is rotatably mounted a gear 209 engaging gear 203, and a clutch roller 210 of rubber or other resilient composition; the clutch roller 210 is of larger diameter than the gear 209, is disposed between that gear and the arm 225, and is secured to that gear for rotation of the two as a unit.

The casting of which arm 225 and hub 224 form parts further includes a small hub 226 (best seen in Figure 10a) surrounding rod 205 adjacent the plate 22; small lug portions 224a and 226a extending downwardly from the respective hubs 224 and 226 (each of these portions being indicated in the front and bottom views of Figures 4 and 5, and portion 224a being also seen in side elevation in Figures 9a and 10); an arm 227 extending forwardly in a vertical plane from the lower portion of hub 224; and a substantially horizontal web 229 joining the two hubs 224 and 226 and reinforcing thereto the rear portion of the top edge of arm 227. As will hereinafter appear, arm 227 is subjected to an upward biasing force; a limit for its upward movement is provided by a felt or like button 230 on top of the web 229, which button normally rests in contact with the bottom of a stop plate 231 secured on top of and extending rightwardly from the block 200 abovementioned, as may be seen in Figures 5, 9 and 10.

It will be understood that the clutch roller 210 is constantly coupled to the sprocket 191 and chain 196 through the train of gears last de-

scribed. The clutch roller 210 is in a side-to-side position/ permitting its engagement with the driving hub 91; but when the mutually integral arms 225 and 227 occupy their normal angular positions about rod 205 (illustrated in Figure 9) the clutch roller 210 is held out of such engagement (i. e., slightly spaced diagonally behind and below hub 91) and is free to rotate as the chain 196 and sprocket 191 may indicate. 10 But as will hereinafter appear, at certain times when the feed nut 84 is disengaged from the feed screw 83, the arm 227 may be rocked slightly downwardly; then the arm 225 will be rocked slightly forwardly, the clutch roller 210 will be 15 engaged with the hub 91, the gear 209 will plane-tate slightly about but will remain engaged with the gear 203, the gear train last described will rotate the sprocket 191 counterclockwise (viewed as in Figure 3), and the advance slide 120 will be driven leftwardly at a relatively rapid rate, pushing against the finger 125 abovementioned and moving leftwardly the carriage 11.

Control of return mechanism

25 Since in the usual operation of the phonograph the advance slide 120 and the carriage 11 are to be returned to their initial positions whenever a record is removed from the mandrel 27 and a fresh record mounted thereon, the phonograph is desirably arranged so that the operation of record manipulation or change will automatically bring into play the return mechanism. In the illustrated embodiment of this invention use is made of an interference piece or guard 30 normally interfering with record manipulation, and requiring movement to a position of non-interference in order to permit that manipulation. The clutch roller 210 is engaged with the driving hub 91 in response to that movement, that roller being automatically disengaged from that hub when the carriage and advance slide have been returned to their initial positions. Other operations are also automatically performed concomitantly with that movement, or 35 with the engagement of the return clutch roller 40 210. These principally affect components of the carriage, and will be described hereinafter—it being convenient at this juncture to note only that these operations include the positive removal of both styli out of engagement with a record on the mandrel 27, the positive disengagement of the feed nut 84 from the feed screw 83, and the positive placement of the finger 125 in its normal position of downward extension into the recess 75a as abovementioned.

50 55 The interference piece or guard is the lever 8, with its fingerpiece 9, already mentioned. As best seen in Figure 29, this lever extends forwardly from a horizontal stud 213 extending rightwardly from the plate 21 quite near the bottom and relatively near the rear of that plate. The righthand surface of the plate 21 may be provided with a recess or sunken portion 214 about the stud 213 and forwardly therefrom to and underneath the end of the mandrel-shielding cylinder 20, so that neither stud 213 nor lever 8 proper need project appreciably beyond that righthand plate surface. In its position of non-interference with record manipulation, as solidly illustrated in Figure 29, the lever 8 may extend approximately horizontally forwardly from the stud 213, wholly within the recess 214. 60 65 In its normal or interfering position, illustrated in Figures 1 and 4 and dottedly indicated in Figure 29, the lever 8 may extend diagonally for-

wardly and upwardly from stud 213 to lie across the open end of cylinder 20, partially in front of the record-ejecting fingerpiece 29 of the mandrel 27. In this latter position the lever interferes with the free manipulation of the fingerpiece 29, and positively prevents the full removal of a record from, or the mounting of a record on, the mandrel 27. The forward portion of the top edge of lever 8 may be thickened, as indicated at 8a, and to this portion may be hinged the fingerpiece 9 already mentioned.

The rear portion of the lever 8 is upwardly widened, forwardly to a point a little forward of the rear of cylinder 20, and here an approximately vertical lug 215 is folded leftwardly from the upper portion of the lever. This lug passes through a kidney-shaped aperture 212 in plate 21 to permit its movement with that of the lever 8; and at the left of the plate 21 the lug 215 is folded rearwardly to form a further lug 216 (as seen in Figures 2 and 5 for example). A spring 217 is tensioned between the lug 216 and a pin 218 extending leftwardly from the upper portion of plate 21; this spring serves to bias the lever upwardly to its normal or interfering position. Against the forward surface of lug 215 is secured the righthand extremity of a horizontal bail 220; this bail serves to transmit the effect of the movement of lever 8 to the lefthand portion of the phonograph, as well as to members of the carriage in manner hereinafter described. The bail 220 passes leftwardly below the rear of the cylinder 20, as seen in Figure 5 for example, and through a suitable aperture 221 in plate 22, seen in Figures 7 and 10. This aperture 221 may be similar to aperture 212 above-mentioned, excepting that its lower portion is forwardly extended to pass other components hereinafter mentioned. The bail 220 is supported near its lefthand extremity by an arm 222 (best seen in Figures 5 and 10a); the forward extremity of this arm is secured to the bail, while the rear extremity of the arm is pivoted to the righthand surface of plate 22—for example on an extension of rod 205 therethrough, this rod being positioned in axial alignment with the stud 213 to which lever 8 is pivoted. The bail 220 will be understood to occupy a raised or upward position (well illustrated for example in Figures 4 and 9a) whenever lever 8 is in its normal or interfering position, and to be moved to a lowered or downward position (illustrated for example in Figures 7 and 10) as the lever 8 is moved to its non-interfering position.

Downward movement of the bail 220 engages the return clutch roller 210 by rocking downwardly an arm 237, next described, this arm causing the necessary downward rocking of arm 227 above-mentioned. The arm 237 extends forwardly in a vertical plane, underneath web 229 and to the right of arm 227, from an elongated hub 236 which is rotatably mounted on a horizontal cross pin 234 extending slightly below rod 205 between the lugs 224a and 226a above-mentioned. The arm 237 may join the hub 236 relatively near the lefthand extremity of that hub, and the rear portion of its top edge may be reinforced to that hub through the substantially horizontal web 235. The arm 237, at the forward extremity of web 235, is offset slightly to the left past the path of the lefthand end portion 229a of the bail 220; the arm 237 is then very considerably widened upwardly by the upwardly extending portion 237a seen in Figures 9 through 11. After extending forwardly a short further

distance, the so widened arm is folded rightwardly to form an approximately vertical apron 238, the upper portion 238a of which is continued to the right further than the lower portion as seen in Figure 4. From the righthand edge of the upper apron portion 238a there is folded rearwardly a lug 240; between this lug and the arm portion 237a there is secured a horizontal cross pin 241; and on this cross pin there is rotatably mounted an elongated collar 242. Downwardly from the center of this collar there is formed, in a vertical front-and-back extending plane, a generally L-shaped pawl 243 having a rearwardly directed foot 244. The normal angular position of the pawl about the cross pin 241 is such as to dispose the foot 244 in the path of downward movement of the bail end portion 229a; this position for the pawl is normally maintained by a spring 246, tensioned between a forwardly curved upward extension 245 of the pawl and a pin 247 extending forwardly from the apron 238, and biasing the extension 245 forwardly into contact with the top of that apron.

15 The entire arm 237 is biased upwardly by a spring 248 tensioned between a pin 249 extending rightwardly from the lug 240 and a pin 250 extending leftwardly from plate 22 above pin 249, as may be seen from Figures 10 and 10a. 20 A limit for upward movement of the arm 237 is established by a horizontal lug 239 folded forwardly from the lower lefthand corner of the apron 238 and surmounted by a felt or like button 251, this button impinging against the bottom of a horizontal lug 228 folded rightwardly from the bottom of the forward portion of arm 227; this structure communicates the upward bias of arm 237 to arm 227, besides making effective on arm 237 the upward movement limit for arm 227 already described. To render arm 227 responsive to a downward rocking of arm 237, a spring 252 is tensioned between a pin 253 extending rightwardly from an upward extension 227a formed from arm 227 and a pin 254 extending leftwardly from arm 237 below pin 253, as seen for example in Figure 10a.

25 In the last portion of downward movement of the bail 220 from its normal position illustrated in Figure 9a, its lefthand end portion 229a will impinge upon the pawl foot 244, carrying the latter downwardly and rocking downwardly the entire arm 237 to the position illustrated in Figure 10; by reason of spring 252, the arm 227 will also be rocked downwardly and arm 225 forwardly, lug 228 remaining in contact with button 251. When the clutch roller 210 comes into engagement with the hub 91 and the return mechanism is thus started in action, the movement of arms 225 and 227 will be completed; but that of arm 237 may continue slightly, button 251 then leaving intimate contact with lug 228, to insure positiveness of engagement of the clutch roller with the hub. To guard, however, against possible jamming of the clutch roller 210 between its support and the hub 91 under abnormal conditions interfering with the return of the carriage, it may be desirable to provide an adjustable stop for the downward rocking of arm 227; this may be done by extending the lug 228 forwardly to over the bottom horizontal post 34 above-mentioned, and passing an adjustable screw 255 upwardly through that post to be impinged upon by the lug 228 under the mentioned conditions.

30 35 40 45 50 55 60 65 70 75 When the lever 8 and bail 220 have been moved

to their downward positions against the force of biasing spring 217, starting the return mechanism in action as above described, they are latched in those positions so that the continuance of operation of the return mechanism will not require the manual holding of lever 8. This latching is accomplished by a substantially vertical lever 260 intermediately pivoted, on a short horizontal stud 259 extending leftwardly from plate 22 above the top of aperture 221, for rocking in a plane close to and parallel with plate 22; this lever is well seen in Figure 10 for example. The lever 260 extends downwardly to bring its lower extremity 261 down to the level occupied by the top of the bail end portion 220a (which may be a little lower than the top of the bail 220 proper, by reason of a vertical narrowing of the portion 220a) when the bail is in its downward position. To the upper extremity of the lever 260 is pivotally secured a flat link member 262 extending rearwardly from lever 260 in a vertical plane. In the rear portion of the link member 262 there is provided a substantially horizontal slot 263, through which passes a pin 264 extending leftwardly from plate 22 in its upper rear portion. The link member 262 is rearwardly biased by a spring 265 tensioned between a pin 266 extending leftwardly from near the top of the link member and a pin 267 extending leftwardly from plate 22 behind pin 266 and slightly above the link member. The impingement of the forward extremity of slot 263 against the pin 264 limits rearward movement of the link member and top portion of lever 260 and forward movement of the lower lever extremity 261. In its limiting forward position, which it will assume in response to spring 265 when the bail 220 has been moved downwardly, the lever extremity 261 is above the bail end portion 220a, latching the bail and lever 8 in their downward positions as shown in Figure 10. The release of this latching is accomplished, as hereinafter described, by moving the link member 262 sufficiently forwardly to move the lever extremity 261 rearwardly off the bail end portion 220a; then the bail and lever 8 will move upwardly in response to spring 217, the bail end portion 220a riding upwardly along the front edge of the lower portion of lever 260, forcing that portion further rearwardly to the position illustrated in Figure 9a and moving the link member 262 further forwardly.

When the return mechanism has returned the advance slide 120 and the carriage 11 to their initial positions, it is automatically put out of action by disengagement of the return clutch roller 210 from the driving hub 91; this disengagement is accomplished, however, without releasing the bail 220 from the latch lever 260, in order that the lever 8 may be kept for the time in its noninterfering position, and for other reasons hereinafter apparent. It is accomplished by rocking the pawl 243 about the cross pin 241 so that the pawl foot 244 moves forwardly from under the bail end portion 220a, thus releasing the arm 237 so that it moves upwardly in obedience to the biasing spring 248, carrying upwardly the arm 227, disengaging the clutch roller 210, and terminating the operation of the return mechanism. To cause this rocking of the pawl there is formed thereon a substantially horizontal cam member 270 extending diagonally forwardly and rightwardly from the righthand surface of the pawl foot 244; and there is secured, at an appropriate rear bottom portion of the carriage 11, a leftwardly extending finger 271

which, as the carriage approaches its most leftward or initial position, passes through the forward portion of the aperture 221 in plate 22 into contact with the cam member 270 near the outer extremity of the latter. While the cam member 270 and finger 271 appear in many views, they are particularly well seen in Figures 5 and 10a; in the latter of these, and in dotted lines in the former, the finger 271 has been shown just as it first reaches contact with the cam member 270. As the leftward carriage return movement continues from this point the finger 271, being incapable of front-and-back movement, forces the cam member to move forwardly, rocking the pawl to effect its disengagement from the bail end portion 220a as and with the effects above-mentioned. Figure 11 illustrates fractionally the arms 225-227 and 237 and associated components after this disengagement—attention being invited, however, to the continuing downward position of the bail 220.

Translating device

It is next desirable to describe in some detail the assembly of carriage 11 and the parts thereby carried, reference being had to Figures 12 through 19. The active component of this assembly is a translating device 280, in which the recording and reproducing styli abovementioned are included. This device is seen in front elevation, with few other components, in Figure 15; it is seen alone in vertical section in Figure 16; and it is seen in Figures 12, 13 and 17 assembled in the carriage with many other components.

The translating device 280 may be of the form and arrangement disclosed in the co-pending application of Michael J. DiToro, Serial No. 187,388, filed January 28, 1938, and is herein described in only so much detail as will suffice to show its relationship to the instant invention. It is of electromechanical nature, for the translation of sound representing electric oscillations into mechanical vibrations, and vice versa. Its basic component is a piezo-electric bending unit of the so-called "bi-morph" type, such for example as is generally disclosed in U. S. Patent No. 1,802,782 to Sawyer. In such a unit two or more thin piezo-electric crystals are secured together face-to-face, with suitable intermediate and outside metal foil electrodes electrically interconnected, in an arrangement such that upon the application of voltage to the electrodes one or more of the crystals will expand longitudinally and another one or more will contract longitudinally, to result in a transverse bending of the unit—and, conversely, upon transverse bending of the unit there will be developed on the several electrodes potentials which are caused by the electrode interconnection to aid each other. Such a unit appears in Figures 16 and 15 as the trapezoidally shaped but approximately vertically disposed unit 281, held in the main frame 282 of the translating device.

This main frame 282, which may be a casting, comprises a substantially vertically disposed, side-to-side extending upper plate portion 283; a lower plate portion 284 continuing a very short distance downwardly from 283 but slightly thickened forwardly; heel portions 285 extending downwardly and rearwardly from each side of 284; a horizontal cross member 285a formed between the rear parts of the heel portions; weight member 287 formed principally forwardly from the bottoms of the heel portions; and a forwardly extending rim or flange 286 beginning at an inter-

mediate point on one side of one of the heel portions 285, running upwardly along that side of that heel portion and of 284 and 283, extending above the upper end of 283, curving in a "nose" 286a, and returning along the other side of 283 and 284 and of the other heel portion 285 to terminate horizontally opposite its point of beginning. Against the front surface of the rim 286 there is held a clamping plate or cover 291, as by screws 292; this cover extends from the nose 286a down to opposite the lower plate portion 284, and its central part is there thickened rearwardly. Between this thickened lower extremity of cover 291 and the lower plate portion 284 there is cemented the lower or wide-end extremity of the bending unit 281, insulated from 291 and 284 by thin electrical insulating pieces such as of "fish-paper." The unit 281 extends upwardly between the cover 291 and the upper plate portion 283 to have its upper or narrow-end extremity a little above the top of 283. While this upper unit extremity is intended to vibrate relative to the rest of the translating device, its vibration is desirably somewhat damped by small pieces 293 of damping material, placed under compression in front of and behind the unit 281 near the upper extremity of the latter by the cover 291 and upper plate portion 283.

To the upper end of the unit 281 is secured a stylus holder 300 in which are held both the recording stylus 301 and the reproducing stylus 302. The holder 300 is formed of relatively compliant material, preferably of a moldable plastic such as is currently available under the trade name "Tenite," for example. This is molded into a form which may be described as comprising a cap portion 299, fitting about and cemented to the upper end of the unit 281; a boss portion 298, extending rearwardly from the cap portion 299, and having the recording stylus 301 cemented therein and extending partially rearwardly therefrom; a thin trapezoidally shaped portion 297, extending upwardly from the rear part of the cap portion 299 in a side-to-side extending plane; and a boss 296, extending rearwardly from the upper part of the portion 297, and having the reproducing stylus 302 cemented therein and extending rearwardly therefrom. In this structure the extending portion 297 provides a compliant coupling of the reproducing stylus 302 to the unit 281; on the other hand, the boss 298 and cap portion 299, by virtue of their immediacy and thickness, provide a substantially rigid coupling of the recording stylus 301 to the unit 281.

The translating device 280 is pivotally mounted for movement in a vertical, front-and-back extending plane, to the extremities of a small, substantially horizontal and side-to-side extending cylinder 323; this pivotal mounting may for example be by bearings 288 located in the lower end portions of the rim 286 abovementioned, these bearings engaging the extremities of the cylinder 323 axially of the latter. By appropriate formation of the weight members and other components, the center of gravity of the translating device is caused to be slightly behind the axis of the cylinder 323 when the translating device is approximately vertical; thus the translating device is biased to rearward movement of its upper portion, to cause stylus engagement with a record R on the mandrel 27.

It will be understood that when sound-representing electric oscillations are impressed across conductors 279 shown in Figure 16 leading to the electrodes of the bending unit 281, there will be

caused an oscillatory front-and-back movement almost wholly of the upper end of the unit, in view of the general translating device mass associated with the lower end of the unit; the recording stylus 301 being assumed in engagement with the rotating record, its oscillatory movement will cause the modulation of the groove being cut by it in the record. On the other hand, assuming the reproducing stylus 302 in engagement with an already-recorded groove of the rotating record, the oscillatory movement imparted by the modulations of the groove to that stylus will be coupled through the compliance of the stylus holder portion 297 to the upper end of the unit 281, causing the oscillatory bending of the unit and the development of corresponding electric oscillations across the conductors 279.

To reduce tendencies of the entire translating device to go into unwanted vibration about its pivotal mounting, at frequencies whereat certain of its parameters resonate with the effective compliance of the moving record, a vibration absorber 305 may be attached at the bottom of the front of the cover 291 and extend upwardly as a cantilever in spaced relationship to that cover. This absorber may be of the general form disclosed in the co-pending DiToro application abovementioned, having as its essential elements a slab 306 of damping material, and a wide, flat spring 307 in contact with the forward surface of, and bent around to hold the free end of, the slab 306. The absorber 305 has been omitted from the showing of the translating device in certain figures in the interest of simplicity.

Support of translating device

The cylinder 323, to which the translating device is pivoted, forms part of a rocker system 320 which is pivotally mounted for movement in a substantially vertical, side-to-side extending plane. This pivotal mounting is effected at the extremities of a front-and-back extending, substantially horizontal cylinder 321 intersecting the center of cylinder 323 and integrally formed therewith; the axis of the cylinder 321 is not only at right angles to that of 323, but is also at a slightly higher level. The function of the rocker system 320 is to permit freedom of movement of the reproducing stylus 302 within a limited range in a side-to-side direction, which is understood to be desirable for the proper "tracking" of the stylus in the grooves of a recorded record; the rocker system accomplishes this function by permitting an appropriate freedom of movement of the entire translating device. It will be understood that since the center of gravity of the translating device, being approximately at the level of the axis of cylinder 323, is always definitely below the axis of the cylinder 321, the reproducing stylus is always lightly biased to a mean position in its free-movement range. The freedom of movement above discussed, being undesirable during operation of the phonograph for recordation, is then eliminated in manner hereinafter mentioned.

The pivoting of the rocker system, at the extremities of cylinder 321, is to a cradle 310 suspended in the carriage 11 from the upper rear portions of the carriage end members 71 and 72. There is there passed inwardly through each of those end members a respective stud 311, having the enlarged threaded portion underneath its head for the thickness of the end member only; this is best seen in Figure 15, in the upper lefthand portion of which the section has

been taken adjacent the lefthand one of these studs. Encircling the inwardly projecting portion of each stud is a respective collar 312 of insulating material, the inner face of each collar being provided with an annular inward extension 312a of reduced diameter. The main cradle frame 313 is a relatively large, substantially upright and side-to-side extending U-shaped member; the upper portion of each arm of the U is apertured to fit freely over the respective inward collar extension 312a, against the inner face of the main portion of the respective collar 312, so that the frame 313 hangs down from the collar extensions as pivots therefor. Centrally of the base or cross-portion 313a of the frame 313 there is secured to the bottom of that base a small, substantially upright and front-and-back extending U-shaped member 314, best seen in Figures 12 and 13; the forward vertical arm of this member 314 may be immediately in front of 313a, but its rear vertical arm may be displaced appreciably behind the rear of 313a. At the center of the top of the frame base portion 313a there is provided a substantially vertical, side-to-side extending lug 315 in elevational alignment with the arms of member 314. It is between this lug 315 and the rear arm of 314 that the rocker system cylinder 321 is pivoted. This pivoting may be accomplished by a front-and-back extending pivot stud 316 passing rearwardly from the front arm of 314 through the lug 315, axially to the front of cylinder 321; and by a pivot stud 317 passing forwardly from the rear arm of 314, axially to the rear of the cylinder 321.

Control of translating device, feed nut, etc., in general

The cradle 310 is so proportioned and so located in the carriage that when the translating device, obeying its bias, engages a stylus with the record, the translating device will extend upwardly from its pivots at about the same angle as that in which the cradle hangs downwardly from the pivot collars 312. If both cradle and translating device have an approximately vertical position, or the slight rearward displacement of their lower portions illustrated in Figure 12, the recording stylus 301 will be in engagement with the record R, at approximately the elevation of the record axis. If however the cradle is rocked forwardly to carry forwardly its lower extremity and that of the translating device to the approximate forward displacement illustrated in Figure 13, then the recording stylus 301 will be moved downwardly and forwardly, and the reproducing stylus 302 will come into engagement with the record. Thus selective control of the engagement of the styli may be and is accomplished by controlling the angular position of the cradle 310 about the pivot collars 312.

To facilitate this control, the cradle is biased to a rearward or recordation position, means later described being provided for moving and holding it forwardly, against its bias, in reproduction position. To provide this bias there is turned leftwardly from the top of the lefthand arm of the cradle frame 313, a little above the lefthand pivot collar 312, a lug 309; from a small block 327 of insulating material secured to this lug a forwardly extending spring 328 is tensioned to a vertical pin 329 extending upwardly from the middle part 75b of the carriage central cross portion 75, as seen for example in Figures 14 and 17. Since the spring 328 operates on the cradle above the

pivot collars 312, it will be understood to bias the cradle to rearward movement.

A limit for this rearward movement is provided, and the recordation position of the cradle 310 is established, by two stop members 330 of electrically insulating material, respectively secured to the inner surfaces of the carriage end members 71 and 72 adjacent the rear of those members and approximately at the level of the rocker system 320. These stop members are formed, and the means immediately impinging thereagainst are arranged, so that when the cradle is moved into its recordation position the rocker system 320 will be first positively levelled and then locked against rotation in the vertical side-to-side extending plane, eliminating the limited freedom of movement which the rocker system provides for the reproducing stylus. The impinging means are two horizontal side-to-side extending "locking" rods 326 provided on the rocker system; thus at the extremities of the so-extending cylinder 323 there are provided small downwardly extending, crank-like webs 325, and the locking rods may extend outwardly from the lower extremities of these webs respectively, toward but not quite into contact with the respective carriage end members 71 and 72 (as seen in Figure 15 for example). The surfaces of the stop members 330 against which these locking rods impinge are diagonally forwardly and downwardly facing surfaces designated as 331; these act as cams as well as stops for the rods 326. When the rearward cradle movement brings either of the rods 326 against a respective one of the surfaces 331, that rod will cam along that surface until further movement is stopped by impingement of the other rod against its respective surface; thus the rocker system is first levelled and then locked against further rotation, as the cradle comes into its recordation position. Figure 13 illustrates in elevation one of the surfaces 331; while illustrating in full the reproduction position of the cradle, this figure shows in dotted lines as 326' the position of the locking rods 326 when the cradle occupies its recordation position (which position is generally illustrated in Figure 12).

The means for moving the cradle 310 forwardly against its bias includes an approximately horizontal lever 318 extending forwardly in a vertical plane from the upper portion of the lefthand arm of the cradle frame 313; this lever extends above the central carriage cross portion 75, and is then folded rightwardly to form a vertical lug 319. A substantially horizontal stud 333 extends forwardly from this lug, and rotatably mounted on the stud 333 is a roller 334 of insulating material. This roller, occupying the position illustrated in Figure 12 when the cradle is in its recordation position, may be forced upwardly to move the lever 318 upwardly and the cradle forwardly into the reproduction position illustrated in Figure 13, by means later described.

While the position of the cradle 310 determines which stylus will engage the record, mere movement of the cradle will at no time disengage both styli from the record. To perform the latter function when required, there is provided means for forwardly retracting the upper end of the translating device, and thus both styli, away from the record. This means may include a substantially horizontal bracket or lug 289 secured to and extending a slight distance forwardly from the top nose 286a of the translating device; a substantially vertical pin 290 of insulating material extending upwardly from the forward ex-

tremity of the lug 289; and a retractor arm 336 having a substantially horizontal, forwardly divergent, wide V-shaped extremity 337, centered behind the pin 290. Normally the retractor arm extremity 337 is out of contact with pin 290, as illustrated in Figures 12 and 13; but the arm may be forwardly moved to bring the extremity 337 against the pin and to rock the pin, translating device and stylus a distance forwardly to the position illustrated for example in Figure 17, simultaneously positively centering the translating device from side to side (i.e., levelling the rocker system 320) by virtue of the V-shape of the extremity. To prevent an undue forward movement of the translating device under any unusual conditions, a suitably bent bracket 338 may hang down from the top carriage cross portion 73 to terminate in a substantially horizontal, rearwardly divergent, wide V-shaped extremity 339 slightly in front of the forward position to which the retractor arm extremity moves the pin 290 as above mentioned.

The retractor arm 336 is pivoted on a stud 340 extending rightwardly from the righthand carriage end member 71 at the rear of the latter and behind the carriage rod 70; the retractor arm extends, closely adjacent end member 71, diagonally forwardly and upwardly from stud 340 to an arcuate slot 341 in that end member, as seen in Figure 7. The arm 336 is folded leftwardly through slot 341, is then formed rearwardly for a distance, and is then formed leftwardly, as seen in Figures 14 and 17, to terminate in the extremity 337 already described. To bias the arm rearwardly, it is extended below the stud 340 and here carries a rightwardly extending horizontal pin 342; and this pin is biased forwardly by a spring 343 tensioned between it and a pin 344 extending rightwardly from the end member 71 near the front of the latter. To actuate the retractor arm, or move it forwardly about its pivot stud 340, there is formed forwardly and downwardly from its portion surrounding the pivot stud a short crank arm 345, best seen in Figure 7; in the extremity of this crank arm is secured a horizontal pin 346 extending leftwardly through an arcuate slot 347 in end member 71. As seen in Figure 12, there extends upwardly from the inner end of this pin a thin link member 348, at the upper end of which is turned leftwardly a vertical minute lug 349. For moving the link member 348 and crank arm 345 there is provided a substantially horizontal lever 351, whose lefthand extremity 350 is formed into a downhanging U-shape and is disposed near the cradle-positioning roller 334. As seen in Figure 14, this lever 351, a little to the right of its extremity 350, has a vertical lug 352 folded downwardly from its rear edge and pivoted on a stud 353 extending forwardly from the square-surfaced middle part 75b of the central carriage cross portion 75; from the lug 352 the lever 351 continues to extend rightwardly almost to the end member 71, and is then formed rearwardly and curved downwardly (as best seen in Figure 12) to have its second extremity pivotally secured to the link member lug 349. It will be understood that the lever extremity 350 is biased to downward movement by the arm-biasing spring 343. A control means hereinafter described stops this downward movement, normally at a lever position which causes the retractor arm 336 to occupy its rearward position; but the control means may be moved to force the lever extremity 350 upwardly, moving the link member 348

downwardly and actuating the retractor arm 336 to retract the translating device and stylus.

The cradle-positioning roller 334 and retractor lever extremity 350 are controlled by respective vertical, side-to-side extending cam plates 361 and 371, which are moved by the control lever 88 above-mentioned and which may now be described.

The control plate 12, in front of which the control lever 88 is positioned, has a horizontal rib or shelf 356 extending rearwardly a short distance from its lower rear surface across almost its full width, seen in plan in Figure 17 and in vertical section in Figure 14. As seen in the latter figure, this shelf rests on and is secured to horizontal ribs 357 extending inwardly from the carriage end members 71 and 72 near their bottoms, this serving to support the control plate 12 to the carriage. Against the bottom of the shelf 356 there is secured a cap member 358, and a circular bearing 359 is formed between these two components at the side-to-side center of the carriage. In this bearing is journaled the forward extremity of a hollow, horizontal shaft 360. The vertical plate 89, at the top of which the control lever 88 is carried, is secured on the forward extremity of this shaft just in front of the control plate 12. Limits for the rotation of the shaft 360 are established by the impingements of a lug 355, extending rearwardly from the plate 89, against the sides of an aperture 354 formed in the control plate 12, into which aperture the lug 355 extends (the aperture, appearing in cross-section in later figures, appearing dotted and the lug partially in full in Figures 12 and 17); this structure prevents any appreciable movement of the control lever 88 rightwardly beyond its recordation position or leftwardly beyond its reproduction position, both above-mentioned. The cam plates 361 and 371 are secured together, the rear of 361 to the front of 371, and together are secured on the shaft 360 a little behind the shelf 356, to extend upwardly from the shaft spacedly in front of the central carriage cross portion 75.

The cam plate 361 is best seen in Figure 14; it is very roughly sector-shaped, extending generally upwardly and leftwardly from the shaft 360; its active cam surfaces are on its periphery. Beginning at its lefthand extremity, the periphery will be seen to be provided with three successive low portions or recesses 362, 364, 366, separated by rather pointed higher portions 363, 365. The recesses are selectively engaged by a detent roller 380; this roller is carried on a horizontal stud 381 extending forwardly from the lower extremity of a detent arm 382. This detent arm is pivoted on a horizontal stud 383 projecting forwardly from the upper portion of the leftward carriage extension 76 above-mentioned just to the left of the end member 72, and from its pivot the arm extends first leftwardly and then downwardly to its lower extremity; it is biased to engage the roller 380 with the cam plate recesses by a spring 384 tensioned between pins respectively provided in the arm and in the carriage extension 76. The detent roller of course engages the respective recesses 362, 364 and 366 when the control lever 88 occupies respectively its recordation, neutral and reproduction positions; and it will be understood that the function of the detent system is to insure the occupation at any time by the control lever 88, shaft 360, cam plates 361 and 371, etc., of one of their three discrete positions.

To the right of the recess 366 the periphery

of the cam plate 361 has a short portion 367 approximating an arc about shaft 360 of radius a little larger than the minimum radial dimension at recess 366; and to the right of the portion 367 the periphery has a short, diagonal, outwardly extending portion 368 leading into a very short terminal portion 369 approximating an arc about 360 of materially larger radius. The cradle-positioning roller 334 is disposed to be passed under by these peripheral portions as the control lever 88 and cam plate 361 are moved. When these occupy their rightward or recordation positions, the relatively smaller-radius peripheral portion 367 is underneath the roller, permitting the latter to occupy its downmost position (as in Figure 12) and the cradle, in full obedience to its bias, to occupy its recordation position. During movement of the control lever and cam plate to their leftward or reproduction positions the diagonal peripheral portion 368 is moved under the roller and cams the roller upwardly, so that when that lever movement is completed the roller is held by the terminal peripheral portion 369 in the materially raised position of Figures 3 and 13, placing the cradle 310 in its reproduction position abovementioned. In the intermediate or neutral position of the control lever and cam plate the roller 334 may still remain in or substantially in its downmost position, although the precise "neutral" position of the cradle is not of importance in view of the retraction of the styli, then effected as next pointed out.

The cam plate 371, while seen in dotted lines in Figure 14, is shown isolatedly in Figure 18, both of these figures assuming a neutral adjustment of the control lever 88. Like cam plate 361, cam plate 371 is very roughly sector-shaped and extends generally upwardly and leftwardly from the shaft 360; but it is of somewhat smaller average radius than cam plate 361 so that it does not interfere with the roller 334. Beginning at its righthand extremity, the periphery of cam plate 371 will be seen to have a diagonal portion 379 leading outwardly to a short portion 378 approximating an arc about shaft 360 of greater-than-average radius; next it has a short diagonal portion 377 leading inwardly to a portion 376 of average radius; finally it has other portions hereinafter mentioned. The retractor lever extremity 350 is positioned to be passed under by the peripheral portions 379, 378, 377 as the control lever 88 and cam plate 371 are moved. When these occupy their rightward or recordation positions the lever extremity 350 rests on the average-radius portion 376 at approximately the righthand extremity of the latter, and when these occupy their leftward or reproduction positions the lever extremity 350 rests on an approximately average-radius mid-position point on the portion 379; in either event the retractor arm 336 is held by the spring 343 in its rearward or unactuated position. As the lever 88 and cam plate 371 are moved into their central or neutral positions, however, the portion 377 or 379, as the case may be, cams the lever extremity 350 upwardly to actuate the retractor arm 336 and retract the translating device and styli from the record. The forward extent of the retractor lever extremity 350 is of course to just behind the cam plate 361, so that it is not influenced by that cam plate.

The cam plate 371 is also employed to control the engagement of the feed nuts 84 with the feed screw 83 and its disengagement therefrom. To provide a mounting for the feed nut a lug

386 is formed downwardly and rearwardly from the central carriage cross portion 75, a little to the right of the center of the carriage (as seen in Figures 12 and 17); from this lug leftwardly to the carriage end member 72 there extends a small horizontal rod 387, on which is rotatably mounted an elongated hub or collar 388. From this collar there is formed downwardly to behind the feed screw 83 a lug 389, and to the lower front surface of this lug the feed nut 84 is secured. The collar 388 is biased to forward rotation of the lug 389, and thus to engagement of the feed nut with the feed screw, by a torsion spring 390 surrounding a reduced-diameter left-hand end portion of the collar and terminally secured to the collar and to the end member 72. To rock the collar 388 for disengagement of the feed nut there extends forwardly from the collar, in a suitable recess in the bottom of the carriage cross portion 75 at about the center of the carriage, an arm 391, whose forward extremity is turned downwardly to form a lug 392; and from this lug a stout pin 393 extends forwardly, almost into contact with the front cam plate 361 and thus into the plane of operation of the cam plate 371. The cam plate 371 is provided with an aperture 394 extending leftwardly from its righthand edge relatively near its periphery; while this aperture may be generally rectangular, its top edge is provided with a downwardly extending cam portion 395 which is approximately vertically above shaft 360 when the control lever 88 and cam plate 371 are in central or neutral positions. When the latter are in leftward or reproduction positions the cam plate 371 is wholly to the left of the pin 393, and when they are in rightward or recordation positions the inner portion of the aperture 394 freely surrounds the pin, which is then disposed near the upper left-hand corner of the aperture; in either case the feed nut is engaged with the feed screw in response to the biasing spring 390. As the control lever 88 and cam plate 371 are moved to neutral position, however, one of the diagonal sides of the cam portion 395 will impinge against the pin 393 and cam it downwardly to the position illustrated in Figure 18, disengaging the feed nut.

A vertical cross-sectional view through the carriage rod 70, appearing as Figure 28, further illustrates the feed nut mounting described in the preceding paragraph. This figure also illustrates in detail the finger 125, abovementioned as arranged for projection into the recess 75a in the righthand part of the carriage cross portion 75 and as forming a pusher for the advance slide 120; the projection of this finger into this recess is also controlled by the cam plate 371, as will next appear. As seen in Figures 14, 17 and 28, the finger 125, whose projection into recess 75a is downwardly through an aperture 126 in the top of the cross portion 75, forms the extremity of a lever 396. This lever is intermediately pivoted on a stud 397 extending forwardly from the square-surfaced middle part 75b of cross portion 75 to the left of stud 353 abovementioned; from its pivoted region the lever extends first upwardly, then rearwardly and then horizontally rightwardly above 75b, and finally downwardly to form the finger 125. The lever 396 is biased, to rotation which withdraws the finger 125 from projection into recess 75a, by a leaf spring 398 secured on top of 75b underneath and bearing upwardly against the horizontal portion of the lever; this spring, seen in Figure 28, is omitted from Figure 14 in the interest of clarity. From

its pivoting region the lever 396 extends, in a vertical side-to-side plane, first a short distance downwardly and then a greater distance diagonally downwardly and leftwardly, and at its extremity is carried a stout pin 399 projecting forwardly almost into contact with the front cam plate 361; this pin is positioned to bear, and by virtue of the biasing spring 398 abovementioned does bear, against the periphery of the cam plate 371, considerably to the left of the retractor lever 350.

The periphery of cam plate 371 to the left of the average-radius portion 376 already mentioned has a short diagonal portion 375 leading inwardly to a short portion 374 approximating an arc about shaft 360 of reduced radius, and then a short diagonal portion 373 leading outwardly to a final portion 372 of average radius; these peripheral portions are moved under the pin 399 as the control lever 88 and cam plate 371 are moved. When these occupy their rightward or recordation positions the pin 399 bears against the average-radius portion 372, and when these occupy their leftward or reproduction positions the pin 399 bears against the average-radius portion 376; in either case the finger 125 is projected downwardly through the aperture 126 into recess 75a. As the lever and cam plate are moved to their central or neutral positions, however, the pin 399 rides down the diagonal portion 373 or 375, as the case may be, into the reduced-radius portion 374, and the finger 125 is withdrawn from the recess 75a.

By the mechanisms so described, excepting as modified in their actions by components hereinafter mentioned, the positioning of the control lever 88 in recordation or reproduction position will cause the engagement of the respective stylus 301 or 302 with the record, the engagement of the feed nut 84 with the feed screw 83, and the projection of the finger 125 into the recess 75a. Conversely, the positioning of the control lever 88 in neutral position will cause the disengagement of both styli from the record, the disengagement of the feed nut from the feed screw, and the withdrawal of the finger 125 from recess 75a.

The manual manipulation of the control lever 88 has already been briefly described; attention may here be directed, however, to certain features adapted to render the manipulations of this lever performable with the least conscious effort, and with desirable special effects. The entire control lever 88, including its rear edge, is inclined forwardly as it extends upwardly from the plate 89; and from the center of the control plate 12 there extends forwardly, substantially to the path of the inclined rear lever edge, a vertical, inverted triangular vane 87. When in central or neutral position the control lever 88 is in alignment with this vane 87; when in recordation position the lever is displaced from the vane in the direction in which the carriage is driven; and when in reproduction position the control lever is displaced from the vane in the direction in which the carriage is to be returned for reproduction of matter already recorded. When the carriage is to be so returned, the operator may place his finger at the right of the control lever 88, overlapping its rear edge, and push leftwardly; this pushing will first move the control lever to neutral position, bringing the operator's finger into contact also with the righthand side of the vane 87, and of course disengaging the feed nut 84. A mere continuance of the same pushing

will now effect a leftward or return movement of the carriage 11. When this movement has progressed to the extent desired the operator, while still continuing the leftward pushing, may simply withdraw his finger sufficiently to bear on the lever 88 only. This will cause the lever to move to reproduction position (the work involved in doing which is less than the work involved in moving the carriage); and further effect of the pushing is obviated by the resulting re-engagement of the feed nut 84, thus positively apprising the operator of the completion of his entire intended manipulation.

When the carriage, with the control lever 88 adjusted for reproduction, has been driven rightwardly until the finger 125 comes into contact with the advance slide 120 and reproduction of previously recorded matter has therefore been completed, the operator may place his finger at the left of the control lever 88, overlapping its rear edge, and push rightwardly; this pushing will first move the control lever to neutral position, bringing the operator's finger into contact also with the lefthand side of the vane 87, disengaging the feed nut 84 and withdrawing the finger 125 from the recess 75a. A mere continuance of the same pushing will now advance the carriage the very slight rightward distance necessary to bring the carriage end member 71 into contact with the button 122 at the extremity of the advance slide arm 121 (as illustrated in the top portion of Figure 28); further movement of the carriage is blocked by this contact, because rightward pressure on the button 122 is so far radially decentralized from the advance slide 120 proper as to cause that slide to bind on the carriage rod 70. Upon sensing this further immovability the operator, while continuing the rightward pushing, may simply withdraw his finger sufficiently to bear on the lever 88 only. This will cause the lever to move to recordation position, re-engaging the feed nut, obviating any further effect from the pushing and positively apprising the operator of the completion of this manipulation. The final movement of the lever to recordation position also causes the re-projection of the finger 125 into the recess 75a; and the top lefthand edge of the advance slide is slightly bevelled as indicated at 120a in Figure 28, so that the finger 125 in completing its re-projection cams the advance slide 120 rightwardly the slight distance required to permit the end part of the finger to resume its normal position at the left of the advance slide. In this way the recording stylus 301 is caused to resume its action on the record a trifle to the right or in advance of the previously recorded matter, positively obviating the danger of obliterating a terminal portion of the latter.

A wholly similar manipulation, simply involving an inherently greater rightward movement of the carriage, is performed if it is desired to restore the recordation adjustment without completing reproduction of previously recorded matter.

Automatic disengagement of styli, feed nut, etc.

In connection with the carriage return mechanism, it was mentioned that certain particular operations affecting the carriage components were automatically performed concomitantly with the movement of the guard lever 8 to non-interfering or downward position, which movement calls into play the return mechanism—these particular operations being the positive removal of

both styli from the record, the positive disengagement of the feed nut, and the positive projection of finger 125 into the recess 75a. It will now be understood that these operations may be effected by the positive placement of the retractor lever extremity 350 and the finger-controlling pin 399 in raised positions, and of the feed-screw-controlling pin 393 in lowered position. These positions may be positively established, independently of the positions of the control lever 88 and cam plate 371 which normally control them, by the operation of a normally inactive, auxiliary vertical cam plate 401 spaced very slightly behind the cam plate 371; this cam plate 401 may be rendered operative by the downward movement of lever 8, through the medium of the bail 220 and associated mechanism. While shown in earlier figures, the structure and operation of the cam plate 401 and its actuation by downward bail movement may be best understood from Figures 5 and 19 through 22.

The auxiliary cam plate 401 is secured to the forward extremity of a sleeve 410 which rotatably surrounds the shaft 360 and extends rearwardly from just behind the cam plate 371; the auxiliary cam plate extends upwardly from the sleeve 410, being, like the other cam plates, very roughly sector-shaped. It and the sleeve 410 are biased to clockwise rotation by a torsion spring 411 having an extremity secured to the cam plate near the middle of the lefthand edge of the latter, extending downwardly and encircling a horizontal stationary stud 412, and then extending upwardly to have its second extremity engaged with the top of the lefthand end member rib 357; the stud 412 may be one which extends forwardly from an appropriate vertical lug 413 extending rightwardly from the lefthand carriage end member 72. The clockwise rotation of the auxiliary cam plate and sleeve 410 is limited by the impingement of the top of a notch 414, formed in the righthand edge of that cam plate, against the top of a vertical pin 415 extending upwardly from the righthand end member rib 357; this establishes the normal or inactive position of the auxiliary cam plate, in which position it is illustrated in Figure 19.

The periphery of the auxiliary cam plate 401, beginning at its lefthand extremity, has a short diagonal portion 402 leading outwardly into a longer portion 403 approximating an arc about sleeve 410 of substantially the average radius of cam plate 371; then the periphery has a short diagonal portion 404 leading further outwardly into a longer final portion 405 approximating an arc about 410 of substantially the greater-than-average radius of portion 378 of plate 371. When the auxiliary cam plate is in its inactive position, the lefthand extremity of the diagonal portion 404 is approximately under the retractor lever extremity 350, and the lefthand extremity of the diagonal portion 402 is approximately under the finger-controlling pin 399. Upon counterclockwise or leftward movement of the auxiliary cam plate each of the elements 350 and 399, unless already occupying a raised position by virtue of the position of the cam plate 371, will be cammed upwardly by the respective one of the diagonal portions 404 and 402, and will be positively held in raised position by the respective one of the portions 405 and 403 pending rightward restoration of the auxiliary cam plate to its inactive position.

In the auxiliary cam plate there is provided an

arcuate slot 406 through which the feed-screw-controlling pin 393 extends. The radius of the outer edge of this slot, in the lefthand end portion 407 normally positioned over the pin 393, is great enough to permit the pin to occupy its raised or feed-screw-engaging position; but at the right of this portion 407 this edge has the short diagonal portion 408 leading inwardly into the portion 409 of reduced radius. Upon leftward movement of the auxiliary cam plate the pin 393, unless already occupying a lowered position by virtue of the position of the cam plate 371, will be cammed downwardly by the diagonal portion 408, and will be positively held in lowered position by the portion 409 pending rightward restoration of the auxiliary cam plate to its inactive position.

Downward movement of the bail 220 will move the auxiliary cam plate 401 leftward from its inactive to its operative position, to perform the three particular operations abovementioned by the influence of the cam plate on the elements 350 and 399 and 393 as just described, through a crank device secured on the sleeve 410 behind the rear carriage cross portion 74 and operated by the bail. The bottom of this cross portion 74 (whose lefthand part is of relatively small, but whose central and righthand parts are of relatively large, front-and-back dimension) is provided with a front-and-back extending groove or channel 416; in this channel the sleeve 410 is effectively journalled, by a horizontal retaining member 417 screwed to the bottom of the righthand part of cross portion 74 and extending underneath the sleeve (the member 417 being suitably apertured to pass or permit access to the screw 81 abovementioned). Immediately behind the cross portion 74 a collar 418 is secured about the sleeve 410. On the lefthand side of this collar is secured an arm 419 which extends first rearwardly from the collar and then diagonally leftwardly and upwardly to form a crank 420; and from the end portion of this crank there extends rearwardly a horizontal stud 421 on which is rotatably mounted a roller 422. When the auxiliary cam plate 401 occupies its inactive position and the bail 220 its raised position, the roller 422 is in contact with or very slightly spaced below the bottom of the bail; but when the guard lever 8 and bail 220 are moved downwardly as above described, the bail will move the roller downwardly, rocking the crank counterclockwise and therefore moving the auxiliary cam plate to its operative position. It will be understood that so long as the bail 220 remains in its downward position—which it was seen to do even after the completion of operation of the return mechanism as above described—the auxiliary cam plate 401 will remain in its operative position, with the styli and feed nut respectively disengaged and the finger 125 in recess 75a. It will further be understood that the disengagement of the styli (and feed nut) by the auxiliary cam plate amounts to a suspension of the control of stylus (and feed nut) engagement by the control lever 88, which lever may for example remain in recordation position throughout this disengagement.

Automatic re-engagement

According to the preferred embodiment of the invention, after the guard lever 8 has been depressed, depressing the bail 220 and operating the return mechanism, this lever and bail remain

in their downward positions and the auxiliary cam plate 401 in its operative position until the rotation of the mandrel is next started; and the operation of starting that rotation automatically restores the lever and bail to their upward positions and the auxiliary cam plate to its inactive position, restoring the response of the styli (and feed nut) to the control lever 88. This preserves complete automaticity. It is furthermore particularly advantageous in that the guard lever 8 is maintained in non-interfering position and the styli in disengaged condition, permitting free record manipulation, up to the instant that the dictator or operator of the phonograph acts positively to start or resume the normal operation of the phonograph; thus for example, should he for any reason desire to remove a record which he has just mounted on the mandrel, as in order to substitute another for it, he may do so without any manipulations other than those of the mandrel and record proper. This upward restoration of the bail 220 and guard lever 8, and the thereby caused restoration of auxiliary cam plate 401 to inactive position, is accomplished by moving the latch lever 269, to release the bail, automatically with the actuation of the starting solenoid 148. The latch lever 269 is so moved by a forward movement of the link member 262, above described to be occupying its rearward position when bail 220 is latched; this link member movement is automatically caused by a finger 144 curving rearwardly and downwardly, behind the rear extremity of the link member, from the righthand end of a horizontal extension 143 formed rightwardly from the arm 140 near the rear of the latter (as best seen in Figures 2, 6 and 10). Actuation of the starting solenoid 148, causing downward movement of arm 140, moves downwardly the finger 144; and this is positioned to contact the rounded rear extremity of the rearwardly positioned link member 262 and to cam the latter forwardly sufficiently to release the bail latching.

From the description of the preceding paragraph it will be understood that after the depression of the guard lever 8, unless the control lever 88 has since been adjusted to neutral position, the next ensuing starting of the record rotation will cause one of the styli to move into engagement with the record. It is desirable that this stylus movement into such engagement be reasonably slow, as distinguished from abrupt and impulsive. For this purpose, and generally to avoid appreciable noises and impacts in the upward movement of the bail 220 which occasions the mentioned stylus movement, I prefer to associate with the bail 220 a dash-pot device 590. This has been omitted from most of the figures in the interest of clarity, but is particularly shown in Figure 34. Its extremities may be pivotally mounted on a horizontal pin 591 secured in the lug 216 which is formed from the upper portion of guard lever 8, and on a horizontal pin 592 extending leftwardly from the plate 21 adjacent the pin 218. The dash-pot device is thus mechanically paralleled with the bail-raising spring 217, whose action it suitably retards.

Automatic establishment of recordation adjustment

When the phonograph is to be used primarily for recordation, it is very helpful that whenever a fresh record is mounted on the mandrel the translating device be automatically adjusted for

recordation upon that record, to obviate the necessity for either manipulation or examination of the translating device by the dictator or operator preparatory to recording on the fresh record. This is accomplished in the phonograph according to the preferred embodiment of the invention by means for positively placing the control lever 88 in recordation position when the guard lever 8 is depressed; it will be understood that the retraction of the styli already described as then occurring will temporarily suspend the full response of the translating device to this lever adjustment but, as has been seen, only until the next starting of the mandrel rotation. The structure for performing this operation, illustrated in detail in Figures 20 through 27, is associated with the rear end of the shaft 360, which is extended beyond the rear end of the sleeve 410. It will be appreciated that by reason of their telescoped relationship, the above described journalling of the sleeve 410 near the rear of the carriage and of shaft 360 near the front of the carriage provide sufficient journalling for both these elements.

On the shaft 360 immediately behind the end of sleeve 410 is secured a collar 425; the rear portion of the collar is slightly enlarged, and from it there are formed two parallel small arms 426 and 427 extending generally rightwardly, 426 above 427, these being understood to be secure with respect to the control lever 88. The end portion of the shaft 360, behind the collar 425, extends a short distance with its full diameter and hollow form, and then for a further distance in a reduced diameter and solid form. Around this entire end portion is fitted a cap member 429; this is held in place axially of the shaft by a screw 428 passing axially into the shaft extremity, but is not itself secured against rotation about the shaft. From the cap member 429 there extends radially outwardly a crank 430. Through this crank near its outer extremity, and rearwardly therefrom, there extends a horizontal pin 431; and from the front face of the crank opposite this pin there extends a short distance forwardly a lug 432, which may for example be formed as a widened head for pin 431. The top arm 426 from collar 425 is extended to have its end portion in the path traversed by the crank lug 432 upon rotation of the cap member 429; the crank 430 is biased upwardly, by means hereinafter described, to contact of its lug 432 with the bottom of arm 426; and the crank is normally latched, by means operating on its lug 432 and hereinafter detailed, in a condition of substantial contact of its lug 432 with arm 426, thus normally causing the crank 430 to extend in an angular direction similar to that of the collar arms 426 and 427 and to be angularly secure with respect to the control lever 88. The front-and-back positions of the components are such that the pin 431 extends underneath the bail 220. The angular positions of the components are such that, assuming the crank to be latched as above mentioned, the pin 431 will be a little below the raised or normal position of bail 220 with the control lever 88 in reproduction position, will be in a somewhat lower position with that control lever in neutral position, and will be immediately below the downward position of bail 220 with that control lever in recordation position; these pin positions have been respectively indicated in dash-dot lines, in the forward-looking cross-sectional Figure 25 as 431'', 431''' and 431'.

Since the movement of the bail 220 to its downward position will force the pin 431 to occupy its most downward position 431', the control lever 88 will be positively placed in recordation position by the downward movement of the guard lever 8. After movement to its downward position, however, the bail 220 has been seen to be held in that position until the next starting of mandrel rotation; accordingly a permanent securing of the crank 430 with respect to the control lever 88 would enforce a recordation adjustment of the latter until after that starting. This would be undesirable, on occasions when it was deliberately intended to reproduce from a record freshly mounted on the mandrel, and the like. Therefore in the preferred embodiment of the invention the crank 430, after positively insuring the placement of the control lever 88 in recordation position, is released from that control lever to permit a deliberate readjustment of the lever if desired; and this release is the function of the latching means mentioned in the preceding paragraph and next described in detail.

Between the arms 426 and 427, a short distance outwardly from the collar 425, there is secured an approximately vertical cross pin 434, and on this pin is rotatably mounted the central hub 435b of an approximately horizontal latch lever 435. From its hub this lever extends inwardly through an elongated aperture 425a in collar 425, and through an elongated aperture 360a in the wall of the hollow shaft 360. The latch lever 435 is biased to forward rotation of its inner extremity by a torsion spring 433 surrounding a reduced-diameter top portion of the hub 435b and terminally engaging the lever and the arm 426; this rotation may be limited, and a normal angular position about pin 434 established for the latch lever, by impingement of the inner lever extremity against the rear extremity of a rod 442 positioned axially within the hollow shaft 360 and hereinafter further mentioned. Outwardly from its hub the latch lever 435 extends to have its outer end portion in front of the path of the crank lug 432; and from this outer end portion there is formed rearwardly and downwardly a latch foot 436 having the top surface 437, forward surface 438, and diagonal rear-bottom surface 439 joining 437 and 438, as seen best in Figure 26. Assuming the crank lug 432 in substantial contact with the arm 426, the bias of the latch lever 435 will cause the top surface 437 of the latch foot to project under the crank lug 432, placing the crank in the latched condition above assumed.

As a means for releasing the latching of the crank for the purpose abovementioned, there is secured to the collar 418, approximately opposite to the arm 419, a lug 440 extending rearwardly to project slightly underneath the inner portion of the latch lever 435; this lug 440 will be understood to be raised by the bail 220 moving downwardly the roller 422 and crank 420 (from the position illustrated in dash-dot lines in Figure 25 as 422''' to the position illustrated as 422'). The rear upper corner of the lug 440 is bevelled, as indicated at 441 in Figures 24 and 25, so that as it impinges against the bottom of the inner portion of the latch lever 435 it cams that portion rearwardly, withdrawing the latch foot 436 from under the lug 432 to release the crank 430. It will be understood that, unless the pin 431 is already in the position 431' (by reason of an already-existing recordation

adjustment of control lever 88), the crank 430 and latch lever 435 will be moving downwardly as the releasing lug 440 is moving upwardly; and the lug 440 is so positioned and shaped as to postpone the completion of the latch-releasing action until the bail 220 has moved downwardly through practically its complete range. This insures the positive placement of the control lever 88 in recordation position, as the operation of the detent roller 380 on the cam plate 361 will complete the necessary minute residual movement into recordation position of that cam plate, with shaft 360, collar 425, etc., in spite of the latch release.

As the mandrel rotation is next started and the bail 220 is therefore restored to its raised position, the releasing lug 440 will of course be removed downwardly from contact with the latch lever 435, and that lever will re-engage the crank 430. If the control lever 88 has been left in the recordation position to which it was moved as above explained, the crank lug 432 will remain held down by the arm 426, and the outer portion of the latch lever will simply move rearwardly in response to its spring 433 to bring the latch foot top surface 437 underneath the crank lug. On the other hand, if the control lever 88 has in the meantime been readjusted to neutral or reproduction position, the latch lever by that movement will have been raised, and the latch foot 436 will have moved rearwardly to above the crank lug 432 in response to the spring 433. As the bail 220 moves upwardly, the crank 430 in response to its bias will also move upwardly until its lug 432 reaches contact with the bottom of arm 426; in doing this the lug 432 will move against the diagonal surface 439 of the latch foot, camming the outer portion of the latch lever forwardly until the mentioned contact of 432 with 426 is substantially effected, whereupon the outer latch lever portion will spring rearwardly again to bring the foot surface 437 under the crank lug.

Special adjustment for reproducing use

At times it may be desired to devote the phonograph primarily or exclusively to reproducing use, as for transcription by a typist from one or more recorded records; it is desirable that then the phonograph be prevented from accidental adjustment into recording condition, and of course that there be suspended the operation of the means for automatically establishing a recordation adjustment upon operation of the guard lever 8. In the phonograph according to the instant invention these objectives are attained by means partially contained within the hollow shaft 360. As seen for example in Figure 20, these means may comprise a rod 443 whose forward end portion is knurled to form a small knob exposedly extending a short distance forwardly from the plate 89 below control lever 88, and which rearwardly extends in a free fit within the shaft 360 for a major portion of the length of the latter; and a rod 442 of smaller diameter, secured axially to the rear end of the rod 443 and extending rearwardly therefrom to have its rear extremity disposed in the path of forward movement of the inner end of latch lever 435 as already mentioned. Independently of the pressure of the latch lever 435 thereon, the rods 442—443 are biased to forward movement by a spring 444 encircling rod 442 and compressed between the rear end of rod 443 and a cylindrical bushing 445 therebehind

secured internally of the hollow shaft 360; the spring 444 is also terminally secured to 443 and 445, and is placed in torsional strain tending to rotate the rods 443-442 counterclockwise as viewed from the front. Both forward and rotational movements of the rods are stopped by a pin 446 extending outwardly from rod 443 into a longitudinal slot 447 in hollow shaft 360, against the front of which slot the pin normally rests as illustrated. The slot 447, however, has an extension 448 from its rear extremity in the direction in which the pin 446 tends to rotate, forming a "bayonet" slot. If the rod 443 be pushed rearwardly, the rods will rotate counterclockwise to bring the pin 446 into the slot extremity 448, wherein it will be held to in turn hold the rods in rearward position. This condition may of course be released by a manual clockwise rotation of the rod 443 to restore the pin to the main slot 447, whereupon the rods will again assume their normal forward position.

When the rod 443 is moved and held rearwardly as just described, the inner portion of the latch lever 435 is moved and held rearwardly by the rod 442, and the outer portion of the latch lever is of course moved and held forwardly; the resulting disengagement of the latch lever 435 from the crank lug 432 will be understood to obviate the automatic establishment of a recordation adjustment, since it suspends the influence on the control lever 88 of a downward movement of the crank 430 by the bail 220. The distance of the latch lever movement by the rod 442, however, is sufficient not merely to cause this latch lever disengagement, but further to bring the latch lever forwardly into the approximate front-and-back position indicated in dash-dot lines in Figure 24; in this position the latch lever outer extremity has a path of movement, upon rocking of the control lever 88, which is intercepted by a biased interference mechanism seen in Figures 21, 24, 26 and 27 and next described.

This mechanism includes a block 475 having its lefthand extremity pivotally mounted on a horizontal stud 476 which passes forwardly through that block into the rear of the rear carriage cross portion 74 a short diagonal distance to the right of and above the collar 418; from the stud the block 475 extends rightwardly adjacent the rear surface of cross portion 74 to approximately the righthand end of the carriage, and in its righthand part the block 475 may be somewhat thickened upwardly. The block 475 is strongly biased to upward rotation by a torsion spring 477 which is wound about a stud 478 and has one terminal in engagement with a pin 479, both 478 and 479 extending rightwardly from the carriage end member 71, and which has its other extremity in engagement with a small lug 474 extending rightwardly from the righthand end of the block 475; this upward movement may be limited, and a normal, approximately horizontal position established for the block 475, by a horizontal stop pin 480 extending rearwardly from the carriage cross portion 74.

Through the righthand part of the block 475 there is provided a horizontal, front-and-back extending hole 481 which, while elsewhere 79 cylindrical, is restricted to approximately semi-cylindrical form at the very back of the block by a thin portion 482 of the block here formed downwardly over substantially the top half of the hole 481. In the hole 481 is freely fitted a 75

small cup-shaped member 485 with its open extremity facing forwardly; this member 485 is biased rearwardly against the block portion 482 by a compression spring 483 having its rear portion disposed within the member 485 and its forward extremity bearing against a cover 484 secured within the front extremity of hole 481. From the member 485 there is formed rearwardly a semi-cylindrical lug 486, which rearwardly projects freely through the semi-cylindrical hole portion underneath the block portion 482, and normally extends as an interference piece to intercept the path of movement of the outer end portion of the latch lever 435 when this is held forwardly by the rod 442 as abovementioned.

It may first be assumed that while the control lever 88 is in either its reproduction or neutral position the rod 443 is manipulated to move and hold forwardly the outer end portion of the latch lever 435; the latter will then extend forwardly above the interference lug 486. The angular position about shaft 360, and the inclination, of the top flat surface 487 of the interference lug 486 are such that although the outer end portion of the latch lever 435 is spaced above the surface 487 when control lever 88 is in reproduction position, the bottom surface of the latch lever proper (as distinguished from its foot 436) will be substantially in contact with the lug surface 487 (as illustrated in dash-dot lines in Figure 26) when the control lever 88 is in neutral position. If it be attempted to move the control lever 88 to recordation position, the latch lever 435 will force downwardly the interference lug 486, and with it the entire block 475, against the force of the biasing spring 477; this spring is of ample strength to cause the upward movement of the latch lever 435 immediately upon release of the control lever 88, the latter being thereby returned to neutral position.

It is of course possible that the rod 443 will be manipulated, to move and hold forwardly the outer end portion of the latch lever 435, while the control lever 88 is in recordation position; in this case that latch lever portion will be brought forwardly underneath instead of above the interference lug 486. But the front top corner of the outer latch lever extremity may be bevelled, as indicated at 435a; and upon the first ensuing movement of the control lever 88 to or through its neutral position this bevelled corner, impinging upwardly against the rear bottom edge of the interference lug 486, will cam that lug (and the member 485 from which it is formed) forwardly against the force of the biasing spring 483, until the bottom of the latch lever upwardly clears the interference lug surface 487. Then the interference lug 486 will spring rearwardly to its normal position; this automatically establishes the conditions of the preceding paragraph, under which the control lever 88 is prevented from effective adjustment into recordation position.

Amplifier switch control

The amplifier 2 is employed both for supplying amplified electric oscillations to the translating device 280 to actuate the latter in a recording operation of the phonograph, and for receiving oscillations from the translating device to be amplified and dispersed in a reproducing operation. This use requires a switch which for recordation will connect the amplifier input with a sound collecting means, and the amplifier output with the translating device conductors 279; and which for

reproduction will connect the amplifier input with the conductors 279, and the amplifier output with a sound dispersing means. An enclosed or shielded switch 450 for performing this function has been mechanically illustrated, in Figures 2, 4, 5, 6 and 29 for example. This switch comprises a ring-shaped stationary member 451 disposed in a vertical, side-to-side extending plane; a long closed-end cylinder 452 extending rearwardly, and a short closed-end cylinder 453 extending forwardly, from the member 451 coaxially therewith, the cylinder 453 being arranged for limited rotation; and switching mechanism (schematically shown in Figure 30) contained within and shielded by these components, and thrown by the rotation of cylinder 453. The stationary ring-shaped member 451 is provided with a foot portion 454, and this is insulatedly mounted on a horizontal shelf 458 in the upper, right-hand rear corner of the phonograph by screws 455 passing upwardly thereinto through the shelf; the insulation is provided by insulating bushings 456 about the screws and a thin sheet 457 of insulating material between the foot portion 454 and shelf 458, as seen for example in Figure 6. The shelf 458 is the extreme upper portion of a bracket member whose vertical main portion 460 is secured against the lefthand side of the rear part of plate 21 (which may be thinned in this part); an extension 459 is formed from the upper part of the front edge of 460, first a little leftwardly and then forwardly and then upwardly in a vertical plane, the shelf 458 being folded over from this extension, as seen for example in Figure 29.

To the center of the front end of cylinder 453 there is secured a small cylindrical spacer 461; to the front of this spacer there is secured a small vertical apron 462; and from the top edge of this apron there is folded forwardly a lug 463, apron 462 and lug 463 extending a distance leftwardly to form a rockable crank for rotating the cylinder 453 to throw the switch. An approximately vertical connecting rod 466 is passed upwardly through the lug 463 near the lefthand extremity thereof, and is loosely and insulatedly secured thereto by insulating bushings 464 and nuts 465 thereabove and therebelow (as seen for example in Figure 4). The rod 466 is moved upwardly and downwardly, to rock the lug 463, by a horizontal bail 470.

This bail 470, best seen for example in Figures 2 through 5, 7 and 29, extends in a side-to-side direction, from adjacent plate 21 to adjacent plate 22, underneath the rear portion of the crank pin 431 abovementioned. As best seen in Figure 5, the bail 470 at its lefthand end is supported by an arm 469 whose forward extremity is secured to the bail, and whose rear extremity is pivoted on the extending rod 205 slightly to the right of the lefthand supporting arm 222 for the bail 220 abovementioned. A righthand support for the bail 470 is provided by an arm 468 whose rear extremity is pivoted on an inward extension of the stud 213 on which the guard lever 8 is pivoted, which extends first forwardly from stud 213 and then leftwardly, and which finally extends forwardly, approximately vertically underneath the top of the connecting rod 466, to have its forward extremity secured to the bail 470. The lower end of the connecting rod 466 is pivotally connected to the supporting arm 468 near the bail 470.

The switch cylinder 453 is lightly biased to clockwise rotation by a spring 471; as best seen

in Figures 4 and 29, this spring is tensioned from the extremity of a rightward extension 472 (formed of insulating material) of the switch apron 462 to the pin 218 therebelow. This biases 5 the connecting rod 466 upwardly, in turn lightly biases the bail 470 upwardly against the crank pin 431, and in turn may provide the abovementioned upward bias of the crank 430. The front-and-back position of the bail 470 is somewhat 10 more rearward than that of the bail 220; and while the crank pin 431 from crank 430 extends both under the bail 220 and above the bail 470, the crank roller 422 from the crank 420 extends only under the bail 220.

So long as the crank lug 432 remains in contact with the arm 426, the position of the bail 470 will be wholly determined by the position of the control lever 88. If that lever be in leftward or reproduction position, the crank pin 431 will 15 be held at its uppermost level indicated as 431' in Figure 25, and the bail 470 immediately thereunder will occupy its upward position, in which it has been illustrated in Figure 3; the switch cylinder 453 will have rotated clockwise to establish 20 the electrical connections abovementioned as appropriate to reproduction. If the control lever 88 be in its central or neutral position, the crank pin 431 will be at the intermediate level indicated as 431'' in Figure 25, and 25 the bail 470 will have been forced downwardly to the intermediate level in which it has been illustrated in Figure 4; the switch cylinder will have rotated to an intermediate angular position, in which there need be no operative connection 30 of the amplifier 2. If the control lever 88 be in its rightward or recordation position, the crank pin 431 will be at its downmost level indicated as 431' in Figure 25, and the bail 470 will have been forced downwardly to its down- 35 most position indicated as 470' in that figure; the switch cylinder will have rotated to a counterclockwise position, establishing the electrical connections abovementioned as appropriate to recordation.

Even though the latch lever 435 be disengaged from the crank lug 432 by an inward positioning of the rods 442-443 (as above described for purely reproducing use of the phonograph) the crank lug 432 will remain in contact with the arm 426 40 by reason of the upward bias of crank 430, and the statements of the preceding paragraph remain applicable. The latch lever 435 was seen, however, also to be disengaged from the crank lug 432 by a movement of the bail 220 into its downward position, in which position that bail holds the crank pin 431 in its downmost level (indicated as 431' in Figure 25 and shown in full in Figure 7); then the bail 470 is held by the pin 431 in its downmost position, establishing a 45 recordation adjustment of switch 450—corresponding to a recordation position of the control lever 88 but maintained even though that control lever be re-positioned. But this condition of non-response of the bail 470 and switch 450 to the 50 position of the control lever 88 is inconsequential, since it exists only throughout an idle period in the operation of the phonograph; normal response will be immediately re-established upon the next starting of mandrel rotation and the attendant re-engagement of the crank lug 432 by the latch lever 435 as above described.

Electrical connections

The fundamental electrical connections of the 55 phonograph are schematically shown in Figure

30. Herein there appear, in simplified showing, a record R; the motor 40; the clutch roller 110 coupling the record and other components to the motor rotationally; the plunger 152 controlling the clutch roller 110 through the coupling rod 153; the lower (starting) and upper (stopping) solenoids 148 and 149, controlling the plunger; the switch comprising the two throw-contacts 162 and 163 respectively in series with the solenoids, and the pole 167 touching the throw-contact of the solenoid opposite to that last actuated; and a motor power circuit comprising conductors 500 and 501 adapted for connection to a suitable power line as through plug 499. A power circuit for the solenoids is branched from the motor power circuit by a conductor 490 leading from conductor 500 to the solenoids through the switch pole 167 and contacts 162 and 163; a conductor 491 leading from conductor 501 to the pole 495 of a switch located within the body of the handpiece 3; and conductors 492 and 493 respectively leading from the throw-contacts 496 and 497 of that switch to the respective solenoids. The switch pole 495 is biased to touch the contact 497 for actuation of the stopping solenoid and preparatory closing of the starting solenoid circuit at 162, and to urge outwardly a start lever 498 to the position in which it is seen to protrude from the handpiece in Figure 1; hand pressure on the start lever 498 will move the pole 495 to leave contact 497 and touch contact 496, as seen in Figure 30, causing the actuation of the starting solenoid and the preparatory closing of the stopping solenoid circuit at 163.

In Figure 30 there appear certain components of the handpiece stand 4. These comprise a cradle 503, seen in Figure 1 to project upwardly from the base of the stand to receive and support one extremity of the handpiece when that is out of use; and an interval switch 504 with its pole biased upwardly to a closed condition and biasing the cradle 503 upwardly, but moved downwardly to open the switch by the weight of the handpiece extremity on the cradle 503. The switch 504 is serially interposed in the conductor 501, to suspend the supply of power to the motor and the conductors 490-491 when the handpiece is rested on the cradle 503. A single-pole double-throw switch 505 is also included in the stand 4, its handle projecting from the stand base as seen in Figure 1; this switch connects a conductor 506 to the conductor 501 selectively on one or the other side of switch 504. The conductor 506, and a conductor 507 branched from the conductor 500, are employed to supply operating power to the amplifier 2; according to the position of the switch 505, the supply of power to the amplifier will be continuous, or subject to control by the cradle 503 similarly to the supply of power to the motor etc.

At the extremity of the handpiece 3 is secured a sound translating device 510, of the reversible-action type which will translate sound which it collects into electric oscillations, or will translate electric oscillations into sound which it disperses; typically it may be of the piezo-electric crystal type. From this sound translating device 510 conductors 511 and 512 lead to the switch 450 abovementioned; and from the translating device 70 conductors 279 abovementioned conductors 521 and 522 lead to the switch 450. The conductors 511 and 521 are connected together and to the low-potential input terminal 531 and low-potential output terminal 533 of the amplifier. The con-

ductors 512 and 522 are connected to the respective poles 513 and 523 of the switch 450.

In the recordation adjustment of the switch 450, in which it is illustrated in Figure 30, pole 513 is thrown to touch a contact 514 connected by a conductor 515 to the high-potential input terminal 532 of the amplifier, and pole 523 is thrown to touch a contact 524 connected by a conductor 525 to the high-potential output terminal 534 of the amplifier; thereby electric oscillations from the sound translating device 510 are impressed on the amplifier input, while amplified oscillations from the amplifier are delivered to the translating device 280. In the reproduction adjustment of the switch 450, pole 513 is thrown to touch a contact 517 connected by a conductor 518 to the high-potential amplifier output terminal 534, and pole 523 is thrown to touch a contact 527 connected by a conductor 528 to the high-potential amplifier input terminal 532; thereby electric oscillations from the translating device 280 are impressed on the amplifier input, while amplified oscillations from the amplifier are delivered to the sound translating device 510. With any or all of the conductors 515, 518, 525 and 528 there may be associated, by way of example in serial arrangement, networks such as have been schematically indicated as 516, 519, 526 and 529, respectively, for suitable shapings, different if desired between recordation and reproduction adjustments, of the frequency-transmission characteristics of the amplifier input and output circuits.

At least the high-potential conductors 511, 521, 515, 518, 525 and 528 are electrostatically shielded by shielding schematically indicated as 508; this is electrically connected with the amplifier shielding 2a, with the air-porous metallic casing 509 of the sound translating device 510, and with the shielding enclosure 451, 452 and 453 of switch 450; this entire shielding may be left floating, grounded, or connected with one of the power supply conductors 500-501, as desired and depending on the nature of the amplifier 2. To permit the shielding potential to be as desired without entailing a similar potential establishment for the entire phonograph frame, the shielding may be kept insulated at all points from that frame; this is the reason for the complete insulation from the frame of the parts of switch 450 as above described, and it may be carried out as to the conductor shielding 508 in any convenient manner. Thus for example all the conductors from the switch 450 have been shown in Figures 6 and 29 passing from the switch in common shielding 508 which is passed rearwardly through a vertical insulating block 449 extending leftwardly from the rear of the bracket portion 460.

Shielding at the same potential as 508 may be supplied for the bending unit 281 of the translating device 280, and for the immediately adjacent fine flexible conductors 279, by the frame 282 of the translating device and the cradle 310 and the rocker system 320; the insulation of this shielding from the phonograph frame is the reason for the use of insulating material for the pivoting collars 312, the insulating stop members 330, the roller 334, the pin 290, the block 321, etc.

In Figure 30 there has been purely schematically indicated, as 450a, electro-static shielding within the switch 450 for the suppression of undesirable coupling between the amplifier input and output circuits.

Review of use

While the use of the phonograph has been made apparent in the foregoing detailed description of its several component mechanisms, it may be briefly reviewed with particular attention to its actual extreme simplicity.

It may first be assumed that the phonograph is to be used for recordation; that the handpiece 3 is resting on the stand 4; that no record is mounted on the mandrel 27; and that the guard lever 8 has been left in its non-interfering downward position, the carriage and advance slide in their initial positions, and the control lever 88 in recordation position, as incidents of the preceding record removal. Preparatorily the dictator may throw the switch 505 to the leftward position of Figure 30 to supply the amplifier with power independently of the cradle switch 504, so that the cathodes of any heater-type tubes therein may begin their fraction-of-a-minute heating; or he may simply remove the handpiece 3 from the stand 4 in sufficient time for that tube heating. The dictator mounts a record on the mandrel (and an annotation slip S in the holder 13) and then, grasping the handpiece 3, brings the sound translating device 510 to adjacent his mouth to serve as a microphone. He exerts pressure on the start lever 498, thereby starting the mandrel rotation and carriage driving, and automatically raising the guard lever 8 to its normal interfering position and engaging the recording stylus 301 with the record. With no pause for these operations, which are immediate, he dictates as desired, releasing the pressure on the start lever 498 to stop the mandrel rotation and carriage driving during pauses. If he wishes to listen back to dictated matter, he releases the pressure on the start lever and performs the appropriate simple leftward manipulation of the control lever 88 above detailed; then, holding the sound translating device 510 near his ear to serve as an earphone, he resumes the pressure on the start lever and listens to the reproduction of the dictated matter. If he wishes to reproduce to the end of the matter already dictated, he may watch for the carriage pointer 16 to reach its normal minute separation from the advance pointer 17; then, or previously if he does not wish to reproduce to the end of that matter, he may release the pressure on the start lever and restore the conditions for further recordation by the appropriate simple rightward manipulation of the control lever 88 above detailed, thereupon resuming dictation as before. During this entire process he may of course make any desired annotations, as of length of dictation sequences and points of error or correction, on the annotation slip S by marking along the righthand edge of the carriage pointer 16; the advance pointer 17 is made of shorter length than the carriage pointer to leave free the forward portion of this edge of the latter for this purpose.

Presently the record space will have been filled with recording, of which the dictator will be apprized for example by the position of the carriage and advance pointers adjacent the righthand extremity of the slip S; he will then, or possibly sooner for any of a variety of reasons, wish to remove the record. Without exerting pressure on the start lever 498 or replacing the handpiece on its stand, he simply depresses the guard lever 8. Automatically the styli will be positively disengaged, the control lever 88 will be positively placed in recordation position, and the carriage

and advance slide will be returned to their initial positions; but without waiting for the completion of this return the dictator will press the ejecting fingerpiece 29 and remove the record from the mandrel. Mounting another record on the mandrel (and changing annotation slips), he may resume the operations of the preceding paragraph, knowing that the phonograph is positively adjusted for recordation independently of the

10 position in which he may have had the control lever 88 at the time of depression of the guard lever 8. This sequence of operations he continues as long as desired; and throughout it no manipulations are required of him excepting that of the start lever 498 for starting and stopping, and of the guard lever 8 and ejecting fingerpiece 29 for record change—and of the control lever 88, in especially simple manner as noted, only if he wishes to listen back.

15 20 If the mounting of a record on the mandrel is for purposes of reproduction therefrom, the control lever 88, although having been positively placed in recordation position by the preceding operation of guard lever 8, may be freely moved to reproduction position before the starting of the mandrel rotation; upon that starting reproduction will be effected, beginning at the start of the record. Or if it is desired to begin reproduction from an intermediate point, the control

25 30 lever 88 is first moved to neutral position, and then by the adjacent vane 87 the carriage is moved rightwardly to bring the pointers 16 and 17 opposite the position at which it is desired the reproduction begin, the control lever 88 finally being moved to reproduction position.

35 40 If it is desired to use the phonograph for reproduction only for a period, the rod 443 is pressed inwardly and the control lever 88 adjusted for reproduction. Thereafter the phonograph may be operated for reproduction from as many consecutive records as desired, with manipulation only of a start-and-stop control (e. g., lever 498), and of the guard lever 8 and ejecting fingerpiece 29 for record change; the control lever 88 will

45 50 continuously remain in reproduction position, excepting as it may be moved into neutral position, for carriage re-positioning, and then back into reproduction position, as incidents of possibly desired backspacing. At the end of any period of such use the rod 443 is rotated clockwise to restore it to its normal forward position, and the restoration of completely normal recordation conditions may be completed by movement of the control lever 88 into recordation position.

55 60 65 Upon completion of any use of the phonograph the handpiece 3 may be rested on the stand 4, automatically stopping the motor. If the switch 505 is in the rightward position (viewed as arranged in Figure 30) the amplifier power supply will be cut off simultaneously with the motor stopping; but if an early resumption of use is anticipated, the switch may be thrown to or left in its leftward position, to maintain the amplifier power supply.

Amplifier

As mentioned initially, and as illustrated in Figures 1, 6, 7 and 8, the amplifier 2 in inverted position may form a support for the phonograph, to provide an extremely compact assembly. The amplifier is provided with a cover 540, of generally similar nature to the cover 6 of the phonograph, and near the corners of the top of this cover are provided the felt or like buttons 539 serving as feet for the entire assembly when arranged in

this manner. While the general details of the amplifier are unnecessary to an understanding of the present invention, certain particular features involving co-operation with the phonograph structure may be described; in their description it is convenient, until otherwise noted, to assume an upright rather than an inverted position for the amplifier.

The amplifier has a main base plate 541 with upturned edges, and a shelf plate 542 spacedly held thereabove by downturned edges secured to the front and back edges of the base plate 541. On the front portion of the shelf plate 542 are assembled most of the components of the amplifier, designated generally as 543, but the amplifying tubes 544 are arranged in a row above the back portion of the shelf plate. Above the shelf plate in front of the tubes is provided a vertical, side-to-side extending baffle 545, which with the cover 549 forms a compartment 546 for the tubes; this baffle is extended between the shelf plate 542 and base plate 541 to form a channel 547 underneath the tubes. Around the tubes the shelf plate is apertured as by holes 548 to provide air communication between the channel 547 and compartment 546.

A flat bottom cover or dust-shield 550 may be provided for the phonograph 1, and is shown in place in Figures 3, 6, 7, 9 and 29; this may be secured to the end plates 21 and 32 at a plurality of points, such as tapped holes 549 seen in the bottom edges of these plates in Figure 5. In that figure there may also be seen a lug 551 formed leftwardly from the bottom of plate 21 near the front of the phonograph, and a lug 552 formed rightwardly from the bottom of plate 32 underneath the cylinder 108. When the amplifier, inverted, is employed as a mounting base for the phonograph, screws 553 are passed upwardly through the inverted amplifier base plate 541, through thin spacers 554, and through the bottom shield 550 of the phonograph into threaded engagement with these lugs 551 and 552, securing the phonograph and amplifier together; these may be seen for example in Figure 6. It will be understood that a sufficient number of lugs such as 551 and 552 will be employed to provide a firm securing together of the phonograph and amplifier, two only having been shown in the interest of simplicity of illustration.

As seen in Figures 6 and 7, the bottom shield 550 of the phonograph is provided with an aperture 555 through which the downward air duct 57 from the fan 53 projects. An aperture 556 in the amplifier base plate 541 registers with this air duct when the phonograph and amplifier are secured together as above described, so that the air stream fanned downwardly through this duct is introduced into the channel 547, passing therefrom through the holes 548 into the tube compartment 546. Through most of the length of the amplifier cover 540 its rear wall, and the rear portion of its top, are cut away, and a grill or louver 558 is fitted in their place as seen in Figures 7 and 8; this louver permits the egress of the air stream from the tube compartment 546, so that the air stream serves to ventilate the compartment and cool the tubes.

Through most of its length and most of its height the rear wall of the phonograph cover 6 is cut away and a louver 559 is fitted in its place; this louver permits the ingress of air to the holes 60 in the motor shields, through which the fan 53 draws air for expulsion through the ducts 57 and 58. It also permits the rearward expulsion

of a second air stream through the rearward air duct 58; and to insure the completeness of expulsion of this stream a baffle 560 may be secured to the inner surface of the louver 559 in surrounding relationship to the duct 58, extending from the duct a short distance in all directions along the louver, and having an inward flange 561 substantially touching the end of the duct 58.

It will be understood that if the phonograph is not mounted on the inverted amplifier, the rearward air duct 58 will carry off practically the entire air output of the fan 53, since the downward duct 57 will be substantially closed by the surface on which the phonograph is rested. The tube compartment 546 of the amplifier, which will then be positioned upright, will be ventilated by convection, particularly through the then-upward horizontal portion of the louver 558.

Securing of covers

To hold the phonograph cover 6 in place there are extended outwardly from each of the phonograph end plates 21 and 32 a respective pair of heavy lugs 570, one near the front and one near the back of the plate, and both slightly spaced above the plate bottom; the cover 6 is slotted to fit over these lugs, and is secured to the pair of lugs at each end of the phonograph by a respective horizontal coupling slide 580 carried by but detachable from the cover. Correspondingly to hold the amplifier cover 540 in place there are extended outwardly from the upturned edge of the base plate 541 at each end thereof a pair of similar lugs 572; and the cover 540, slotted for these lugs, is secured to each pair of lugs by a respective similar detachable coupling slide 580. As seen in Figure 6, the coupling slides 580 have portions extending underneath the respective lugs, whereas the main portions of the slides extend upwardly to top flanges in engagement with acute shoulders formed outwardly from the covers, these shoulders being designated as 571 for the phonograph cover 6 and as 573 for the amplifier cover 540 (which has just been referred to as though in upright rather than inverted position). In view of the complete similarity of the several coupling slides and associated features of the covers, further description thereof is presented with respect to the lefthand slide 580 for the phonograph cover 6—it being understood, of course, that the similarity of the slides with each other entails a reversal of formations and movements, as expressed in terms of front-and-back dimension, between the lefthand and righthand slides. Reference is invited particularly to Figures 5 and 31 through 33b for a description of the specified slide in operative position, after which its movements for cover detaching, and finally for its own detaching from the cover, are described.

For almost its full front-and-back dimension the bottom of the end of the cover 6 is cut away up to the level of the bottom of the phonograph frame lugs 570, as indicated by the edge 575 in Figure 31, and upwardly from this edge are formed slots 576 in which the lugs 570 are disposed, when the cover is in place. For a distance rearwardly from each of the slots 576 the edge 575 is cut away to a slightly higher level than the rest of that edge, as indicated by the portions 575a. For a considerable distance forwardly from each of the slots 576, and for a short distance upwardly from the edge 575, the inner cover surface is provided with slight recesses or grooves 577. Between the slots 576 the cover is out-

wardly thickened from the edge 575 for a short distance upwardly, and the thickening may extend partially above the slots 576 as seen in Figures 32a and 33a; the thickening terminates at its top in the acute shoulder 571.

The main portion of the coupling slide 580 is a narrow plate 581 horizontally arranged in a vertical plane just outwardly of the thickened portion of the cover; from this plate 581 the slide has an inward top flange 582 and inward end flanges 579 at least substantially abutting against the outer cover surface, the top flange 582 for most of its length having an acutely angled lower edge 583 hooked over the acute cover shoulder 571. Inwardly from the bottom of the plate 581 are formed two horizontal lugs 584; each of these slide lugs extends under a respective one of the frame lugs 570 and for a further distance forwardly therefrom, when the slide is in its operative position. From the forward portions of the inner edges of the slide lugs 584 there are formed thin upward projections 585, which are normally disposed within the rear portions of the cover grooves 571 above mentioned. These projections prevent outward movement of the bottom of the slide 580; the engagement of the acutely-edged top flange 582 with the acute cover shoulder 571 prevents outward movement of the top of the slide, or downward movement of the whole slide; and the forward portions of the slide lugs 584 immediately beneath the cover edge 575 prevent upward movement of the whole slide. The slide is accordingly secured against all excepting front-and-back sliding movement with respect to the cover. Since the rear portions of the slide lugs 584 are immediately underneath the frame lugs 570, the latter are held in the slots 576, and the cover is accordingly secured in place.

The slide 580 is prevented, by the impingement of the projections 585 against the frame lugs 570, from being moved rearwardly; it may, however, be moved forwardly to carry the slide lugs 584 out from under the frame lugs 570, thereby disengaging the latter to permit the removal of the cover. In such removal the slide 580 will of course accompany the cover; but after the cover removal the slide 580 may be moved rearwardly further than when the cover was in place, to bring the upward projections 585 opposite the cover slots 576, and the lugs 584 wholly under those slots and the slightly cut-away edge portions 575a. Now the bottom of the slide may be swung outwardly, approximately about the shoulder 571 as a pivoting region, so that the slide lugs 584 wholly clear the cover edge 575 and the slide becomes wholly detached from the cover. Its attachment to the cover is of course the reverse of the detaching operation; and after attachment, to guard against unwanted detachment, a stop pin 586 may be screwed into the rear one of the cut-away edge portions 575a to prevent sufficient rearward movement of the slide for detachment.

The rear top edges of the slide lugs 584 may be slightly bevelled, so that a tight engagement of the frame lugs 570 may be provided without risking a failure of the slide lugs to pass under those frame lugs when the cover is being secured in place. If desired, a re-inforcing bottom flange 587 may be extended inwardly from the plate 581 between the slide lugs 584, excepting in the region just behind the forward one of those lugs, which region comes opposite the forward frame lug 570 when the slide is moved forwardly

in the process of placing the cover in or removing it from its normal position.

While my invention has been disclosed in terms of a specific embodiment thereof, it will be understood that various features of this embodiment may be widely altered without necessarily constituting a departure from the true spirit and scope of the invention. In many of the appended claims I undertake to express the scope of the invention broadly, subject however to such limitations as the state of the art may impose.

It will further be understood that by the phraseology of "positively" establishing a specified condition, or the like, there is meant the constraining of the apparatus to that condition; this phraseology is intended to apply even though the apparatus permits that condition, under certain circumstances in the use of the phonograph, to have been already otherwise established.

I claim:

1. In a phonograph having a record support onto and from which a record may be mounted and removed and means for rotating the supported record: the combination of means for starting the operation of said rotating means; a member movably secured in the phonograph and biased into a position wherein it interferes with exchange of records on said support, but movable into a position of non-interference; means for latching said member in said non-interfering position; and means, rendered effective by said starting means, for releasing said latching means.

2. In a phonograph having a record support onto and from which a record may be mounted and removed and means for rotating the supported record: the combination of means for starting the operation of said rotating means; a member movably secured in the phonograph and movable into and out of a position wherein it interferes with exchange of records on said support; and means, rendered effective by said starting means when the same is next operated after member movement out of said position, for restoring said member to said position.

3. In a phonograph having a record support and a record-cooperating translating device: the combination of a carriage for said translating device drivable adjacent said support away from an initial position; mechanism for returning said carriage to said initial position; a movable control member biased to a first position and latchable in a second position; means for placing said returning mechanism in operation, arranged for and responsive to engagement by said control member as said member is moved to said second position; and means, operated by said carriage upon its arrival at said initial position, for disengaging said last mentioned means from said control member.

4. In a phonograph having a record support and a record-cooperating translating device: the combination of a carriage for said device; means for driving said carriage in a path adjacent said support away from an initial position; an advance device for indicating the position of farthest advance of said carriage, having at least a portion disposed in said path in advance of said carriage for movement thereby away from an initial position; and reverse driving means, immediately connected with said advance device and influencing said carriage through the medium of said advance device, for returning said advance device and carriage to their initial positions.

5. In a phonograph having a record support,

a record-cooperating translating device, and driving mechanism: the combination of a carriage for said device movable in a path adjacent said support; means for engaging said carriage with said driving mechanism for advancement thereby along said path; an advance device disposed in said path in advance of said carriage for indicating the position of farthest advance thereof, having a portion on which advancing force is ineffective to move said advance device and on which a portion of the carriage impinges when advanced out of engagement with said mechanism; and means, rendered effective by said engaging means for advancing said advance device portion out of contact with said carriage portion and rendering effective an advancing force of the carriage on said advance device.

6. In a phonograph having a record support and a record-cooperating translating device: the combination of a carriage for said device movable in a path adjacent said support; an advance device disposed in said path in advance of said carriage for indicating the position of farthest advance thereof, having two portions against which the carriage may impinge, and movably responsive to pressure by the carriage against one of said portions only; and movable means, carried in the carriage, for controlling the impingement of the carriage against the advance device selectively between said two portions.

7. In a phonograph having a record support and a record-cooperating translating device conditionable in at least one translational condition and in another condition with respect to the record: the combination of control means connected with said device to control its condition; a carriage for said device movable in a path adjacent said support; an advance device disposed in said path in advance of said carriage for indicating the position of farthest advance thereof, having two portions against which the carriage may impinge, and movably responsive to pressure by the carriage against one of said portions only; and means, controlled by said control means, for controlling the impingement of the carriage against the advance device selectively between said two portions.

8. In a phonograph having a record support, a record-cooperating translating device, and driving mechanism: the combination of a carriage for said device movable in a path adjacent said support; control means for engaging said carriage with said driving mechanism for advancement thereby along said path; an advance device disposed in said path in advance of said carriage for indicating the position of farthest advance thereof, having two portions against which the carriage may impinge, and movably responsive to pressure by the carriage against one of said portions only; and means, controlled by said control means, for controlling the impingement of the carriage against the advance device selectively between said two portions.

9. In a phonograph having a record support, a record-cooperating translating device, and driving mechanism: the combination of a carriage for said device movable in a path adjacent said support; control means for engaging said carriage with said driving mechanism for advancement thereby along said path; an advance device disposed in said path in advance of the carriage for indicating the position of farthest advance thereof; and means, operated by said control means upon manipulation thereof to effect said engagement when the carriage is at

least substantially in contact with said advance device, for slightly advancing said advance device.

10. In a phonograph having a record-supporting mandrel: the combination of a record-cooperating translating device; a carriage for said device movable along said mandrel; a shaft transverse of said mandrel carried by said carriage; means for selectively conditioning said translating device, responsive to the angular position of said shaft; and mutually distinct means for rocking said shaft, comprising a manually movable control lever associated with the front portion of said shaft, and crank-and-bail means associated with the rear portion of said shaft.

15 11. In a phonograph having a frame and a record support: the combination of a translating device including record-engageable stylus means; a carriage for said device; a control lever carried by the carriage; a cam plate in the carriage controlled by said lever and controlling said stylus means as to record engagement; a member movably secured to said frame; and an auxiliary cam plate in the carriage, controlled by said member and operable to place said stylus means out of record-engaging position independently of the position of said control lever.

12. In a phonograph having a frame, a record support and a record-cooperating translating device: the combination of a carriage for said device; feeding means with which said carriage is engageable to drive the same adjacent said support; a control lever carried by the carriage; a cam plate in the carriage controlled by said lever and controlling the engagement of said feeding means; a member movably secured to said frame; and an auxiliary cam plate in the carriage, controlled by said member and operable to place said carriage out of engagement with said feeding means independently of the position of said control lever.

30 13. In a phonograph having a frame, a record support, and a record-cooperating translating device: the combination of a carriage for said device; means for driving said carriage in a path adjacent said support; an advance device disposed in said path in advance of said carriage; a finger included in said carriage movable into and out of a position to transmit to said advance device the advancing force of the carriage; controlling means carried by the carriage adjustable to positionally control said finger; and means, operable from said frame, for placing said finger out of said position independently of the adjustment of said controlling means.

35 14. In a phonograph having a frame and a record support: the combination of a record-cooperating translating device; a carriage for said device drivable adjacent said support; a movable member extending from said carriage; and bail means, comprising a pair of bails movably secured to said frame and disposed on opposite sides of the path of said member, for both response to and control of said member.

40 15. A phonograph including a frame, said frame comprising a pair of spaced plate members and a tubular member extending therebetween; and a record-supporting mandrel supported by said frame and extending within said tubular member, one of said plate members being open across the end of said tubular member for the mounting and removal of a record on and from said mandrel.

45 16. A phonograph including a frame, said frame comprising a pair of spaced plate members and a tubular member extending therebetween

and provided with a longitudinal aperture; a record-supporting mandrel supported by said frame and extending within said tubular member; and a record cooperating translating device movable along said tubular member and extending inwardly through said aperture.

17. A phonograph comprising a pair of spaced plate members; an apertured tubular member extending therebetween; a record-supporting mandrel within said tubular member; a rod parallel with said tubular member; a record-cooperating translating device; a carriage for said translating device supported on and movable along said rod; and means, included in the carriage and bearing on said tubular member, for holding the carriage against rotation about said rod.

18. In a phonograph including a record support, a record-cooperating translating device conditionable in at least one translational condition and in another condition with respect to the record, and means for relatively moving the supported record and the translating device: the combination of a start-and-stop control for said moving means; control means connected with said device, movable at least to one translation position and to another position and normally effective on said device to correspondingly condition the same; a movable control member; means, rendered effective by said control member, for positively placing said control means in said translation position and rendering the same ineffective on said device; and means, rendered effective by said start-and-stop control in a starting operation thereof subsequent to the operation of said last-recited means, for rendering said control means again effective on said device.

19. In a phonograph including a record support, a translating device including record-engageable recording and reproducing styli, and means for relatively moving the supported record and the translating device: the combination of a start-and-stop control for said moving means; control means for said styli normally effective thereon, movable at least to recordation and reproduction positions to place a corresponding one of said styli in record-engaging position; a movable control member; means, rendered effective by said control member, for positively placing said control means in a predetermined one of its said recordation and reproduction positions and rendering the same ineffective on said styli; and means, rendered effective by said start-and-stop control in a starting operation thereof subsequent to the operation of said last-recited means, for rendering said control means again effective on said styli.

20. In a phonograph including a record support, a translating device including a stylus movable into and out of record-engaging position, and means for relatively moving the supported record and the translating device: the combination of a start-and-stop control for said moving means; control means for said stylus, movable at least to one translation position and to another position and normally effective in said positions respectively to place said stylus in and out of record engagement; a movable control member; means, rendered effective by said control member, for rendering said control means ineffective on said stylus, positively placing said control means in said translation position, and positively placing said stylus out of record-engaging position; and means, rendered effective by said start-and-stop control in a starting operation thereof

subsequent to the operation of said last-recited means, for rendering said control means again effective on said stylus.

21. In a phonograph having a record support onto and from which a record may be mounted and removed, a translating device including record-engageable stylus means, and means for relatively moving the supported record and the translating device: the combination of a start-and-stop control for said moving means; control means for said stylus means normally effective thereon to control the same as to record engagement; a movable member in such cooperative relationship to said record support that a movement of said member is rendered an incident of the exchange of records on said support; means, rendered effective by said member in said movement thereof incident to record exchange, for rendering said control means ineffective on said stylus means; and means, rendered effective by said start-and-stop control in a starting operation thereof subsequent to the operation of said last-recited means, for rendering said control means again effective on said stylus means.

22. In a phonograph having a record support onto and from which a record may be mounted and removed, a record-cooperating translating device conditionable in at least one translational condition and in another condition with respect to the record, and means for relatively moving the supported record and the translating device: the combination of a start-and-stop control for said moving means; control means connected with said device and normally effective thereon to control the condition thereof; a movable member in such cooperative relationship to said record support that a movement of said member is rendered an incident of the exchange of records on said support; means, rendered effective by said member in said movement thereof incident to record exchange, for rendering said control means ineffective on said device; and means, rendered effective by said start-and-stop control in a starting operation thereof subsequent to the operation of said last-recited means, for rendering said control means again effective on said device.

23. In a phonograph having a record support onto and from which a record may be mounted and removed, a record-cooperating translating device conditionable in at least one translational condition and in another condition with respect to the record, and means for relatively moving the supported record and the translating device: the combination of a start-and-stop control for said moving means; control means connected with said device, movable at least to one translation position and to another position, and normally effective on said device to correspondingly condition the same; a movable member in such cooperative relationship to said record support that a movement of said member is rendered an incident of the exchange of records on said support; means, rendered effective by said member in said movement thereof incident to record exchange, for positively placing said control means in said translation position and rendering the same ineffective on said device; and means, rendered effective by said start-and-stop control in a starting operation thereof subsequent to the operation of said last-recited means, for rendering said control means again effective on said device.

24. In a phonograph having a record support, a record-cooperating translating device condi-

tionable in at least one translational condition and in another condition with respect to the record, driving means for advancing said device away from an initial position relative to the supported record, and an advance device advanced by said driving means away from an initial position to indicate the position of farthest advance of said translating device: the combination of a start-and-stop control for said driving means; control means connected with said translating device and normally effective thereon to control the condition thereof; means arranged for operation at will to effect the return of said translating and advance devices to their initial positions; means, rendered effective by said last-recited means in said return-effecting operation thereof, for rendering said control means ineffective on said translating device; and means, rendered effective by said start-and-stop control in a starting operation thereof subsequent to the operation of said return-effecting means, for rendering said control means again effective on said translating device.

25. In a phonograph having a record support, a record-cooperating translating device conditionable in at least one translational condition and in another condition with respect to the record, and driving means for advancing said device away from an initial position relative to the supported record: the combination of a start-and-stop control for said driving means; control means connected with said device, movable at least to one translation position and to another position and normally effective on said device to correspondingly condition the same; means arranged for operation at will to effect a return of said device to its initial position; means, rendered effective by said last-recited means in said return-effecting operation thereof, for positively placing said control means in said translation position and rendering the same ineffective on said device; and means, rendered effective by said start-and-stop control in a starting operation thereof subsequent to the operation of said return-effecting means, for rendering said control means again effective on said translating device.

26. In a phonograph having a record support, a record-cooperating translating device conditionable in at least one translational condition and in another condition with respect to the record, driving means for advancing said device away from an initial position relative to the supported record, and an advance device advanced by said driving means away from an initial position to indicate the position of farthest advance of said translating device: the combination of a start-and stop control for said driving means; control means connected with said translating device and normally effective thereon to control the condition thereof; means arranged for operation at will to effect the return of said translating and advance devices to their initial positions; and means, rendered effective by said last-recited means in said return-effecting operation thereof, for rendering said control means ineffective on said translating device.

27. In a phonograph having a record support and a record-cooperating translating device conditionable in at least one translational condition and in another condition with respect to the record: the combination of control means connected with said device, movable at least to one translation position and to another position to correspondingly condition said device; a movable control member; mechanism arranged for oper-

ation to constrain said control means into said translation position, and operated by said control member; and means, rendered effective by said mechanism as it completes its said operation, for releasing said control means from the constraint of said mechanism.

28. In a phonograph having a record support and a record-cooperating translating device conditionable in at least one translational condition and in another condition with respect to the record: the combination of control means connected with said device, movable at least to one translation position and to another position to correspondingly condition said device; a movable control member; mechanism, rendered effective by said control member, for constraining said control means into said translation position; and latch means, included in said mechanism and operated thereby as the same completes its constraining action, for releasing said control means.

29. In a phonograph having a record support onto and from which a record may be mounted and removed, a translating device including a stylus movable into and out of record-engaging position, and means for effecting a relative movement of the supported record and the translating device: the combination of control means for said stylus, effective thereon at least during said movement, movable at least to one translation position and to another position to place said stylus in and out of record-engaging position, respectively; a movable member in such cooperative relationship to said record support that a movement of said member is rendered an incident of the removal of a record from said support; and means, operated by said member in said movement thereof incident to record removal, for positively placing said control means in said translation position and positively placing said stylus out of record-engaging position.

30. In a phonograph having a record support and a record-cooperating translating device, and means for advancing said device from an initial position relative to the supported record: the combination of mechanism for returning said device to its initial position; a clutch included in said returning mechanism and engageable to render said mechanism operative; a movable member in such cooperative relationship to said record support that a movement of said member is rendered an incident of the exchange of records on said support; and means, rendered effective by said member in said movement thereof incident to record exchange, for engaging said clutch.

31. In a phonograph having a record support and a record-cooperating translating device, and means for advancing said device from an initial position relative to the supported record: the combination of mechanism for returning said device to its initial position; a clutch included in said returning mechanism and engageable to render said mechanism operative; a movable member in such cooperative relationship to said record support that a movement of said member is rendered an incident of record removal from said support; and means, rendered effective by said member in said movement thereof incident to record removal, for engaging said clutch.

32. In a phonograph having a record support and driving means: the combination of a translating device for cooperation with the supported record, advanced from an initial position relative to the record by said driving means, and returnable to said initial position; an advance device,

advanced by said driving means from an initial position to indicate the position of farthest advance of said translating device, and returnable to said last-mentioned initial position; reverse driving mechanism included in the phonograph and operable to return said translating and advance devices to their initial positions; and

means, comprising an operative connection between said mechanism and said advance device, for causing every operation of said mechanism which returns said translating device to its initial position to be effective to positively place said advance device in its initial position.

CHARLES W. DANN.
